UNITED STATES PATENT OFFICE

2,022,293

METHOD OF AND APPARATUS FOR MANIPULATING TALKING MACHINE OR PHONOGRAPH RECORDS

Rudolph F. Mallina, New York, N. Y., assignor, by mesne assignments, to Radio Corporation of America, New York, N. Y., a corporation of Delaware

Application July 18, 1929, Serial No. 379,285
Renewed April 26, 1935

43 Claims. (Cl. 274—10)

My invention relates to apparatus for manipulating talking machine or phonograph records, such as centrally perforated disk records of a type well known to the art; my invention also comprehends the manipulation of disks other than talking machine or phonograph records, said last named disks being utilizable for any desired purpose, control or otherwise.

In accordance with my invention, sound is reproduced, independently of manual control, from each of a plurality of talking machine or phonograph records having different diameters and grouped or stacked upon a turntable.

More particularly, the aforesaid records are disposed on said turntable in any desired or predetermined order, the respective topmost records being removed therefrom after each period of sound reproduction.

Further in accordance with my invention, a turntable carrying a group of talking machine or phonograph records is elevated step-by-step to remove the respective topmost records therefrom, sound being reproduced from each topmost record after each step of elevation of said turntable.

Further in accordance with my invention, relative movement is effected between a turntable and its stem to disengage a turntable-carried talking machine or phonograph record from the latter, said record being removed from above said turntable in response to the action of previously applied force.

More particularly, relative movement, as aforesaid, is obtained by elevating said turntable with respect to its stem and the record is removed from above said turntable in response to the action of a member biased into engagement with the periphery of said record previous to disengagement thereof from said stem.

Further in accordance with my invention, elevation of said turntable, as aforesaid, is discontinued by a member moved by the aforesaid biased member.

Further in accordance with my invention, a turntable carrying a plurality of talking machine or phonograph records is moved upwardly step-by-step by pawl and ratchet mechanism, the latter being rendered temporarily non-operative each time that one of said records is moved from said turntable.

More particularly, said pawl is disengaged from said ratchet in response to a control effected by a member shifting the respective topmost records laterally after the respective periods of sound reproduction.

More particularly, a turntable controlled as

just stated or in an equivalent manner is adapted for supplementary manual control whereby it may be elevated or lowered at will.

Further in accordance with my invention, there is associated with a turntable having a plurality of talking machine or phonograph records grouped thereon a stem which projects upwardly beyond the upper surface of said turntable and extends through the center perforations of said records, said turntable being elevated independently of said stem.

More particularly, said stem is rotatable with said turntable and comprises spring fingers biased into engagement with adjacent surfaces of said records.

Further in accordance with my invention, a member or lever for removing a talking machine or phonograph record from a turntable is utilized for controlling movement of a sound reproducing instrumentality coactable with individual records carried by said turntable; more particularly, said member or lever functions to position said sound reproducing instrumentality above a record on said turntable just prior to initiation of a period of sound reproduction.

Further in accordance with my invention, a sound reproducing system wherein a plurality of talking machine or phonograph records are stacked on a turntable is so arranged that operation of the motive device for said system is discontinued after sound has been reproduced from the lowermost record on said turntable.

Further in accordance with my invention, the upper face of a turntable comprises a spiral groove of relatively great pitch and terminating in a suitable control groove, as one that is eccentrically disposed with respect to the turntable center.

My invention resides in the method, system, apparatus, features of construction and combinations of parts of the character hereinafter described and claimed.

For an understanding of my method and for an illustration of some of the many forms my invention may take, reference is to be had to the accompanying drawings, in which:

Figure 1 is a perspective view, partly broken away, of talking machine or phonograph mechanism constructed in accordance with my invention;

Fig. 2 is a plan view, partly broken away, of a part of the mechanism shown in Fig. 1;

Fig. 3 is a plan view, partly in horizontal section, corresponding generally with Fig. 2 but with the motor board omitted;

- Fig. 4 is a front elevational view of my novel talking machine or phonograph mechanism;
- Fig. 5 is a vertical sectional view, partly in elevation, and is taken substantially on the line 5—5 of Fig. 2 looking in the direction of the arrows;
- Fig. 5a is a vertical sectional view of a modified form of turntable utilizable in accordance with my invention;
- 10 Fig. 5b is a plan view of the turntable shown in Fig. 5a;
- Fig. 6 is a transverse, vertical sectional view, partly in elevation, and is taken substantially on the line 6—6 of Fig. 2 looking in the direction of the arrows;
- 15 Fig. 7 is a horizontal sectional view, partly in plan, and is taken on the line 7—7 of Fig. 6;
- Fig. 8 is a side elevational view of the mechanism shown in Fig. 7;
- 20 Fig. 9 is an enlarged, transverse, vertical sectional view, partly in elevation and with parts omitted, and is taken substantially on the line 9—9 of Fig. 2 looking in the direction of the arrows;
- 25 Fig. 10 is an enlarged, vertical sectional view, partly in elevation and with parts omitted, and is taken substantially on the line 10—10 of Fig. 2 looking in the direction of the arrows;
- Fig. 11 is an enlarged, vertical sectional view, 30 partly in elevation, and is taken substantially on the line 11—11 of Fig. 2 looking in the direction of the arrows;
- Fig. 12 is a horizontal sectional view, partly in plan, and is taken on the line 12—12 of Fig. 9, 35 and also showing in dot and dash lines some of the mechanism above said line 12—12;
- Fig. 13 is an enlarged, front elevational view of turntable elevating and lowering mechanism;
- Fig. 14 is a transverse, vertical sectional view, 40 partly in elevation, and is taken on the line 14—14 of Fig. 13 looking in the direction of the arrows;
- Fig. 15 is an enlarged, vertical sectional view and is taken on the line 15—15 of Fig. 2 looking 45 in the direction of the arrows;
- Figs. 16, 17, 18 and 19 are enlarged, side elevational views, partly in section, illustrating different positions of mechanism for imparting movement to a tone arm or other member carrying a 50 sound reproducing instrumentality; and
- Fig. 20 is a chart showing movements effected by different cams.
- Referring particularly to Fig. 1, there is illustrated a suitable cabinet, casing or housing C, 55 usually substantially rectangular, and supporting, Figs. 4 and 10, a suitable transverse wall, member or motor board m. A top or cover C1, ordinarily, is pivoted to the aforesaid cabinet, casing or housing C. In the example shown and 60 as illustrated in Figs. 4, 5 and 10, suitable horn structure H is disposed below the motor board m, sound waves issuing from said horn structure and passing to an audience or listener through an orifice or passage, not shown, in the front 65 casing wall.
- Above the motor board m is a compartment or chamber to which access may be had by elevating the aforesaid cover C1. Disposed in said compartment is a turntable T movable along a 70 substantially vertical path as hereinafter described and adapted to carry one or a plurality of talking machine or phonograph records R, each of which, in the example illustrated, is a centrally perforated circular disk having, on 75 each substantially flat face, spiral groove struc-
- ture disposed inwardly of the disk periphery and utilizable for the production of sound, each spiral groove terminating in and communicating with a circular groove e eccentrically disposed with respect to the record perforation.
- When the turntable T carries a plurality of talking machine or phonograph records R, as it usually does, they are disposed thereon in superposed, grouped, or stacked formation, that is, in such relation that one record directly engages 10 and is supported by another. In accordance with my invention, sound is reproduced from the topmost record of the turntable-supported stack of records by coaction therewith of a stylus s of a sound box S, or equivalent, whereupon said 15 topmost record is suitably removed from said turntable, as by passage thereof from right to left, Fig. 1, to one side of the aforesaid compartment. Sound is then reproduced from the now topmost record of said stack of records and 20 it, in turn, is passed from right to left, Fig. 1. In this manner, sound is reproduced in succession from the respective topmost records of the group or stack of records, said records being grouped, in more or less irregular relation, to one 25 side of the turntable T.
- More specifically, one of the many forms of mechanism utilizable in accordance with my invention is illustrated as comprising a frame member 1 spaced below and carried by the motor 30 board m. Any suitable construction may be utilized for this purpose such, for example, as the bolts 2 and spacing washers 3, Fig. 10. This frame member 1 constitutes a support upon which is mounted or which carries the herein- 35 after described mechanism.
- Depending from the frame member 1 and suitably connected thereto is a motive device M of any suitable construction and from which power is obtained to rotate the turntable T and to 40 periodically operate the automatic mechanism hereinafter to be described. In the example shown, the motive device M is an electric motor of the induction disk type and comprises a disk or armature 4 carried by a suitably journaled, 45 vertical motor shaft 5, there being suitable coil structure, not shown, for rotating the disk 4 and the thereto-secured shaft 5.
- Referring to Figs. 5, 6, 7 and 8, the shaft 5 is shown as having a sleeve 6 pinned or otherwise 50 suitably secured thereto for rotation therewith. A clutch wheel or spider 7 is similarly secured to the sleeve 6. Freely rotatable on the sleeve 6 is a disk or member 8 having pivoted thereto at 9, Fig. 7, a clutch segment 10 having a tooth 10a 55 coactable with the aforesaid clutch wheel 7 and biased in a clockwise direction, Fig. 7, by a helical spring 11, or the like, one end of said helical spring 11 being connected to a pin 12 upstanding from the clutch segment 10 and the other end 60 thereof being connected to a pin 13 upstanding from the disk 8.
- Rotatable with the disk 8 is a gear 14 which meshes with a gear 15 rotatable on a member 16 upstanding from the frame member 1. Rotatable with the gear 15 is a gear 17 which meshes with a gear 18 rotatable with a hub 19 pinned or otherwise suitably secured to a cam shaft 20 for 65 rotation therewith.
- As hereinafter described, the aforesaid gear 14 70 is periodically secured by the above described clutch mechanism to the shaft 5 to rotate therewith. During such periods, the machine is said to be "in cycle" and, during these periods, the automatic mechanism operates under the control 75

of gear 14 and the mechanism leading to the cam shaft 20.

Initiation of automatic cycle as effected by a record R

5 Referring to Fig. 10, the frame member 1, at one corner thereof, is shown as provided with a circular opening or passage having a sleeve 21 fixed therein because connected to said frame member 1 to which a member 22 is also connected. 10 Rotatable in the member 21 is a hollow adapter member 23, anti-friction members 24 preferably being interposed in any suitable manner between the sleeve 21 and member 23. As illustrated in Fig. 10, a washer 25 may be utilized to retain some of the anti-friction members 24 in position, the washer 25, if desired, carrying a flanged member 26 receiving the lower part of a sleeve 27 coacting with the aforesaid adapter member 23. 15 Sleeve 21 presents an inner curved surface corresponding with the curved upper part of adapter member 23 upon which said sleeve 27 is loosely mounted. The adapter member 23 and sleeve 21 are connected by a pin or member 28 by virtue of which said sleeve 27, as shown in Fig. 10, is oscillatable in either direction in a plane corresponding with the plane of the paper.

Connected to the sleeve 27 is one end of the vertical section of a tone arm or taper tube 29, the other substantially horizontal end of which has one end of the usual conduit-forming goose neck 30 oscillatorily connected thereto, the aforesaid sound box S being carried by the other end of goose neck 30. As illustrated in Fig. 4, adjacent ends of the tone arm 29 and goose neck 30 carry the respective stop members 31 and 32 utilizable as hereinafter described.

With a construction of the character just described, sound waves developed by the sound box diaphragm pass through the goose neck 30, tone arm 29 and the adapter member 23. From the latter, said sound waves pass to and through the horn structure H, the passage at the small end thereof being suitably held in alinement with the passage through the adapter member 23.

45 Due to the character of the connection between the adapter member 23 and the sleeve 21, the sound box S, goose neck 30 and the adjacent section of the tone arm 29 are freely movable in a direction from right to left, Fig. 2, or vice versa. Due to the character of the connection between sleeve 27 and adapter member 23 and comprising the pin 28, the vertical section of tone arm 29 is tilttable in either direction in a plane corresponding 50 with the plane of the paper, Fig. 10, sound box S moving either up or down during such tilting movement provided that the latter is of sufficient extent to cause engagement between the coacting stop members 31 and 32.

60 Referring particularly to Figs. 2, 3 and 10, the aforesaid sleeve 27 is shown as having a member 33 secured thereto for movement therewith. Member 33 comprises an arm or extension 33a to which a member 34 is secured, the latter preferably being resilient in character and utilizable as hereinafter described.

The other arm or extension 33b of member 33 comprises a substantially horizontal section 33c utilizable as hereinafter described, Figs. 5 and 10. 65 Beyond the horizontal section 33c, arm 33b comprises a substantially vertical section 33d to which a rack member 35 is secured in any suitable manner. As clearly illustrated on the drawings, the frame member 1 is apertured as indicated at 36 so that the aforesaid horizontal section 33c of

arm 33a may be disposed below the plane thereof.

Pivoted on one end of a lever 37 is a pawl 38 having an edged surface facing and coactable with the teeth of the aforesaid rack member 35. Pawl 38 comprises a depending lug or projection 38a coactable with the adjacent surface of lever 37 and having a spring 38b connected thereto and to lever 37 for biasing pawl 38 in a clockwise direction, Fig. 3.

Lever 37, in the example shown, is pivoted on 10 the aforesaid cam shaft 20 and, for this purpose, it may be suitably secured to a hub 39 loosely mounted on the upper end of said cam shaft 20 and maintained in the position shown in Figs. 9 and 10 by a screw 40, or equivalent.

15 As illustrated particularly in Fig. 3, the lever 37 is suitably biased in a counter-clockwise direction as, for example, by a helical spring 41, one end of which is secured to a lug depending from said lever 37 and the other end of which is secured to a post or member 42 upstanding from the frame member 1, said post 42 coacting with the adjacent end of lever 37 to limit movement thereof in a counter-clockwise direction, Fig. 3.

20 Lever 37, adjacent its end to which the spring 41 is connected, has levers 43 and 44 pivoted to the upper surface thereof. As hereinafter described, the lever 43 is maintained in the position illustrated in Fig. 3 when sound is to be automatically reproduced from a plurality of records in 25 succession.

25 Lever 43, at the end thereof to the left, Fig. 3, is adapted to coact with a lug 45a upstanding from an arm 45b of a lever 45 spaced above the frame member 1 and pivoted on a member 46 upstanding therefrom. Lever 45 is suitably biased in a clockwise direction, Fig. 3, as by a helical spring 47, one end of which is connected to a lug projecting from the aforesaid arm 45b of lever 45 and the other end of which is connected 30 to the aforesaid post 42.

35 Lever 45 comprises an arm 45c having a hook-shaped end 45d adapted to coact with one end of the aforesaid clutch crescent 10 as clearly illustrated in Fig. 7.

40 During a period of sound reproduction, the sound box S moves along the arc of a circle in a clockwise direction, Fig. 2, under the influence of the spiral sound reproducing groove of the topmost record R rotating with the turntable T. The tone arm 29 similarly moves, as does the rack member 35, Fig. 3, due to the hereinbefore described connection between the latter and the tone arm 29. The rack teeth of member 35 are 45 so arranged that they idle past the pawl 38 during movement of said member 35 as just described.

45 Eventually, the sound box stylus s passes from the spiral sound reproducing groove and into the eccentric groove e. As a result, the stylus s, sound box S and tone arm 29 are moved in a direction the reverse of the direction taken thereby during the period of sound reproduction. The rack member 35 is similarly moved in reverse direction and, in so doing, adjacent teeth or serrations thereon exercise a clutching effect on pawl 38. Due to engagement effected by the lug 38a of pawl 38 with the adjacent surface of lever 37, the latter is moved by the rack member 35 in a clockwise direction, Fig. 3. By reason of 50 such movement, the end of lever 43 to the left, Fig. 3, engages the lug 45a of lever 45 to move the latter in a counter-clockwise direction, Fig. 3, and disengage the hook-shaped end 45d of arm 45c of lever 45 from the end of clutch crescent 55 70 75

10. Thereupon, spring 11 swings the latter about its pivot to effect engagement between the clutch crescent tooth 10c and the clutch wheel 7. In this manner, the gear 14 is connected to the constantly rotating shaft 5, said gear 14 initiating operation of the cam shaft 20 whereby the cycle of the automatic mechanism is started.

Cam mechanism

10 Referring particularly to Fig. 9, the cam shaft 20 is shown as journaled in bearings formed, respectively, in the frame member 1 and in a depending section 1a thereof.

15 The aforesaid hub 19 was described as secured to and rotatable with the cam shaft 20. To this hub 19, a cam K is secured for rotatable movement therewith. As hereinafter described, the cam K controls and actuates mechanism for removing a record R from the turntable T after 20 each period of sound reproduction and for moving the sound box S laterally toward and from the center of the turntable T.

20 In the example shown, a cam K1 is secured to and rotatable with the aforesaid gear 18 which, 25 as described, provides the driving connection for the cam shaft 20. The cam K1 is utilizable, as hereinafter described, in a three-fold manner: to retain the hook-shaped end 45d of the arm 45c of lever 45 out of the path of the rapidly 30 rotating clutch crescent 10 during continuance of the cycle of the automatic mechanism; to prevent chattering engagement of parts of the clutch mechanism; and to gently move the sound box stylus s into the spiral sound reproducing 35 groove at the initiation of each period of sound reproduction.

35 In the form of my invention herein illustrated, the cam shaft 20 is disposed in substantially a vertical direction and is utilizable for rotating a second cam shaft 50 disposed in substantially 40 a horizontal direction and journaled in bearings formed, respectively, in the aforesaid depending section 1a of frame member 1 and in a second depending section 1b of the latter, Fig. 9. 45 A gear 51 pinned to and rotatable with the cam shaft 20 meshes with a similar gear 52 pinned to and rotatable with the cam shaft 50, the relation of said gears 51 and 52 being such that rotation of cam shaft 20 through an angle of 360 50 degrees effects the same amount of rotative movement for the cam shaft 50.

55 A cam K3 is secured to and rotatable with the cam shaft 50. Cam K3, as hereinafter described, operates mechanism for elevating the sound box S just after the conclusion of each period of sound reproduction and for lowering the same just prior to the initiation of each subsequent period of sound reproduction.

60 Cam shaft 50 also carries a cam K4 utilizable for elevating the turntable T after each period of sound reproduction.

65 *Discharge of the respective topmost records R from the turntable T after each period of sound reproduction*

70 Pivoted to and spaced above the upper surface of frame member 1 is a lever 53 having, at one end thereof, a cam follower 54 coactable with the aforesaid cam K. Lever 53 is suitably biased in a clockwise direction, Fig. 3, as by a helical spring 55, one end of which is secured to a lug projecting therefrom and the other end of which is secured to a post or member upstanding from the frame member 1. The end of lever 53 removed from the cam follower 54 is pivoted to one

end of a link 56, the other end of which is pivoted to an arm 57 carried by and oscillatable with a shaft or member 58 extending substantially in a vertical direction through the motor board m and frame member 1 and journaled in a bearing 5 1c of the latter.

Below the frame member 1, an arm 59 is secured to the shaft 58 for oscillatory movement therewith, said arm 59 having pivoted thereto one end of a link 60, Figs. 11 and 12, the other 10 end of said link 60 being pivoted to a lever 61 pivoted at 62 to an arm 63 forming an extension of a collar 64 freely oscillatable on the aforesaid member 22, Fig. 10. The end of arm 63 is flanged and provided with a threaded opening for the 15 reception of a screw 65 coactable with the flanged end of lever 61, the latter being suitably biased into engagement with said screw 65, as by a helical spring 66 connected to said lever 61 and to the arm 63.

20 Below the aforesaid arm 59, a second arm 67 is secured to the shaft 58 for oscillatory movement therewith. Arm 67 carries a laterally projecting pin or member 68 slidable in a slot 69a of a lever 69 pivoted on a vertical member 70 carried by a boss comprised in the extension 1b of frame member 1, Figs. 9 and 12.

25 As illustrated particularly in Fig. 11, the aforesaid shaft 53, above the frame member 1, carries a sleeve 71 movable with said shaft 58 and 30 terminating in bifurcations 71a through which extend a pin or member 72 for pivotally mounting an ejector rod or member 73. The latter comprises a tail section 73a with which coacts a screw 74 threaded into a transverse section of 35 the aforesaid furcations 71a.

35 Referring particularly to Figs. 1, 2, 4, 5 and 11, the ejector rod 73 is shown as carrying a depending freely rotatable member 75 having a record-engaging rim 75a. Projecting laterally 40 from the rod 73 is a stem 76 having a member 77 freely rotatably mounted thereon about substantially the longitudinal axis of said stem 76 and suitably held in position thereon, as by a screw 78, Fig. 11, said member 77 having a rec- 45 ord-engaging rim 77a utilizable as hereinafter described.

50 Initiation of the cycle of the automatic mechanism initiates clockwise movement, Fig. 3, of cam K. As a result, lever 53 is swung in a clockwise 55 direction, Fig. 3, under the influence of spring 55. Due to the chain of mechanism hereinbefore described, such movement of lever 53 causes counterclockwise movement, Fig. 1, of the ejector rod 73.

55 During progressive movement of cam K in the direction just described, the member 75, carried by the end of rod 73, is brought closer and closer to the group of records R rotating on the turntable T and eventually, at its rim 75a, engages the topmost one of said records. Before engagement is thus effected, the member 77 has passed above said topmost record and engages the same at its rim 77a, the beveled or inclined surface 77b of member 77 to the left of rim 77a, 60 Fig. 5, usually engaging the edge of the topmost record and, during continued movement of member 77 from right to left, Fig. 5, causing slight elevation of the members 77, 75 and the adjacent end of rod 73. When the parts have come to the 65 position just described, namely, wherein the rim 75a of member 75 is in engagement with the aforesaid topmost record, that record, and all of the group of records, of course, are rotating with the turntable T. However, since the mem- 70 75

bers 75 and 77, preferably, are freely rotatable, friction is greatly reduced and the aforesaid topmost record is not damaged or are parts of the mechanism unduly strained.

5 The member 77 is spaced above the lower surface of member 75 a distance substantially equal to the thickness of ordinary commercial records. Hence, said member 75, at its rim 75a, engages only the topmost record of the group of records 10 and not the one therebeneath. Preferably, the member 75 is provided with a beveled or inclined surface 75b below the rim 75a, Fig. 5. Due to this construction, should records of different diameters be arranged on the turntable T as shown 15 in Fig. 5, for example, the member 75 presents a nonabrading surface, namely, the above described beveled or inclined surface 75b, to the upper face of the second record from the top while moving thereabove although engagement therewith may 20 not necessarily be effected.

After the rim 75a of member 75 engages the edge of the topmost record R as described above, said last named record discontinues further movement of said member 75. Accordingly, the 25 members 75, 77, rod 73 and associated mechanism including the cam roller 54 come to rest and so remain for a brief period. However, movement of cam K continues in a clockwise direction, Fig. 3, the lower surface thereof separating from the 30 cam roller 54.

As hereinafter more fully described, mechanism constructed in accordance with my invention is adapted to reproduce sound from records of a plurality of different diameters arranged in 35 any desired order on the turntable T. More specifically, ordinary commercial ten and twelve inch records may be employed in accordance with my invention.

In the form of my invention herein shown, the 40 aforesaid member 75 comes into engagement with the periphery of a twelve inch record after the cam K has moved through an angle of approximately 35 degrees. Where a ten inch record is disposed uppermost on the turntable T, said 45 member 75 comes into engagement with the periphery thereof after the cam K has moved through an angle of approximately 42 degrees.

As hereinafter described, the topmost record R of the stack of records, no matter whether 50 ten or twelve inch, is released from the turntable stem later in the automatic cycle than is marked by movement of cam K through an angle of either 35 or 42 degrees, as aforesaid. Furthermore, before said topmost record R has been 55 released from the turntable, the sound box S has been elevated from said topmost record.

Accordingly, when said topmost record R is freed from the restraint imposed by the turntable, the spring 55 becomes effective to further 60 swing lever 53 in a clockwise direction, Fig. 3, such movement of lever 53 causing further counter-clockwise movement, Fig. 1, of rod 73 and the members 75 and 77 carried thereby. The last described movement of lever 53 is typically a 65 snapping movement limited by return of cam roller 54 to cam K. As a result, the topmost record R is ejected or propelled from the turntable T and passes in a direction from right to left, Fig. 1. Shortly thereafter, cam K becomes 70 effective to swing lever 53 in a counter-clockwise direction, Fig. 3, and expanding the spring 55. As a result, rod 73 is returned toward the position occupied thereby before the beginning of the automatic cycle.

75 During the same cycle and under the influence

of cam K, rod 73 makes another excursion in a counter-clockwise direction, Fig. 1. This action will be discussed hereinafter.

Cam K1 and the controls effected thereby

The cam K1 as illustrated, for example, in Fig. 3 is shaped substantially as an annulus concentrically disposed with respect to the cam shaft 20. The inner face of cam K1 comprises a cam surface having a single low area 79. Coactable 10 with said inner face of cam K1 is a cam roller 80 projecting laterally from the free end of arm 45b of lever 45.

When the cycle of the automatic mechanism is initiated, rack 35 causes movement of lever 45 15 in a counterclockwise direction, Fig. 3, to disengage the hook-shaped end 45d of lever 45 from engagement with the end of clutch crescent 10. In so doing, the cam roller 80 is moved substantially out of the low area 79 of cam K1. 20 As soon as the cycle of the automatic mechanism is initiated, the cam K1 moves in a clockwise direction, Fig. 3, and the high area thereof comes into engagement with the cam follower 80. As a result, lever 45 is maintained in the position to 25 which it is swung in a counterclockwise direction, Fig. 3, out of the path of the rotating clutch crescent 10 until cam K1 has moved through an angle of 360 degrees. At this time, the low area 79 of cam K1 has returned to the 30 position from which moved as described above and the arm 45b of lever 45 is swung in a clockwise direction, Fig. 3, under the influence of spring 47 to position the hook-shaped end 45d of arm 45c of lever 45 in the path of the rotating clutch crescent 10. Lever 45 is free to move clockwise at this time because, earlier in the automatic cycle, the rack member 35 has been moved from engagement with the pawl 38. When engagement is effected as just described, the 40 clutch segment 10 is swung in a counter-clockwise direction, Fig. 7 against the action of spring 11 to thereby disconnect the automatic mechanism from the source of power.

The outer face of cam K1 comprises a cam 45 surface having a low area 81 and a high area 82, Fig. 3. Coactable with said outer face of cam K1 is a cam roller 83 projecting laterally from a lever 84 pivoted on the aforesaid upstanding member 16. Lever 84 is suitably biased 50 in a clockwise direction, Fig. 3, as by a helical spring 85, one end of which is secured thereto and the other end of which is secured to a member or post upstanding from the frame member 1. One end of lever 84 carries a laterally 55 projecting roller 86 coactable with a cam surface 87 of the aforesaid disk 8. The other end of lever 84 comprises spaced prongs 88 and 89.

When the cycle of the automatic mechanism is initiated, movement of cam K1 in a clockwise 60 direction, Fig. 3, effects counter-clockwise movement of lever 84, Fig. 3, due to the fact that the low area 81 of said cam K1 recedes from the cam roller 83 carried by said lever 84. As a result, the lateral roller 86 of lever 84 is moved out of 65 the path of the cam surface 87 of disk 8 and is so held during movement of said disk 8 and during operation of the automatic mechanism.

After the cam K1 has moved through nearly 70 360 degrees, the high area 82 thereof coacts with 75 the cam roller 83 of lever 84. As a result, lever 84 is further swung in a counterclockwise direction, Fig. 3, and coacts at prong 88 or 89 with the aforesaid member 34 to cause gentle movement of the sound box stylus into the spiral sound 76

reproducing groove of the next record R from which sound is to be reproduced. This action will be more fully hereinafter described. The particular prong, whether 88 or 89, which thus engages the member 34 depends upon the diameter of the topmost record R on the turntable T.

Immediately after the high area 82 of cam K1 recedes from the cam roller 83 of lever 84, the low area 81 of said cam K1 comes into registering relation with said cam roller 83 and lever 84, under the influence of spring 85, swings in a clockwise direction, Fig. 3, to thereby move the roller 86 into the path of the cam surface 87 of disk 8. As the cycle of operation ceases, said cam surface 87 engages said roller 86 to thereby prevent movement of disk 8 until another cycle of automatic operation is initiated. In this manner, chattering engagement is prevented between the clutch crescent tooth 10a and adjacent teeth of the clutch wheel 7, this action occurring under the influence of the fixed spring 11 were the aforesaid roller 86, or equivalent, omitted.

25 Sound box elevating mechanism

Referring particularly to Figs. 9 and 10, a cam roller 90 is shown as coacting with the aforesaid cam K3. Roller 90 is carried by a depending arm 91a of a lever 91 pivoted on a member 92 supported by the aforesaid depending section 1a of frame member 1 and an adjacent depending section 1d of said frame member 1. The free end of lever 91 comprises an apron or elongated section 93 coactable with the horizontal section 33c of member 33.

Soon after the cycle of automatic operation is initiated, cam K3 functions to swing the lever 91 counter-clockwise, Fig. 10. In so doing, apron 93 engages the horizontal section 33c of member 33 and, during continued movement of lever 91 in a counter-clockwise direction, Fig. 10, the member 33, sleeve 27 and tone arm 29 are swung clockwise, Fig. 10, about the pin 28.

As a result, rack member 35 is disengaged from pawl 38. Accordingly, lever 37, under the influence of spring 41 swings in a counter-clockwise direction, Fig. 3, until the end thereof, removed from the pawl 38, engages the post 42. This is the position occupied by said lever 37 during any period of sound reproduction. Lever 45, however, for the reason hereinbefore stated, does not return at this time to the position occupied thereby during a period of sound reproduction due to the action thereon of cam K1.

55 When the tone arm 29 is swung clockwise, Fig. 10, as described above, the stop members 31 and 32 are first engaged and thereafter the sound box S and its stylus s are elevated from the topmost record R of the group of records 60 on the turntable T. This occurs prior to the time that said topmost record R is released from the turntable stem. The cam K3 continues to hold the sound box S elevated while it is swung, as hereinafter described, first counter-clockwise 65 and then clockwise, Fig. 1, the horizontal section 33c of member 33 sliding upon the apron 93 during this action. Finally, just prior to the conclusion of the automatic cycle of operation, the cam K3 lowers the apron 93 to permit counter-clockwise movement, Fig. 10, of the tone arm 29. As a result, the sound box stylus is lowered into engagement with the now topmost record R on the turntable T just outwardly of the spiral sound reproducing groove, the stop members 31 and 32 separating somewhat after

the sound box stylus s engages said last named record.

Elevation of the turntable T

Referring particularly to Fig. 6, the aforesaid sleeve 6, which as stated is rotatable with the motor shaft 5, is shown as comprising an upper extension 6a of reduced cross-sectional configuration and extending both above and below the turntable T which, as shown in Fig. 6, is in its 10 lowermost position. Upwardly of the turntable T as the latter appears in Fig. 6, the sleeve extension 6a comprises a plurality of resilient fingers 6b forming the turntable stem and each terminating in an enlarged section 6c to thereby 15 form a chamber flaring downwardly for the reception of a metallic ball 94, or the like, which rests upon the upper end of a rod 95 freely slidable within the aforesaid sleeve 6a. Ordinarily and as illustrated particularly in Figs. 5 and 6, 20 the aforesaid resilient fingers 6b are formed by suitably slotting a sleeve and thereafter disposing the unslotted base thereof on the upper end of the upper extension 6a of sleeve 6. Rod 95 comprises an enlarged base section 95a through 25 which and to both sides thereof a pin 96 extends, opposite sides of said pin 96 extending, respectively, through aligned, elongated slots formed in opposite sides of the sleeve 6. Outwardly of sleeve 6, each end of pin 96 extends into a ring or collar 30 97 which is thereby slidably mounted on the sleeve 6. Rod 95 is suitably biased into the position shown in Fig. 6 as, for example, by a helical spring 98 disposed within the sleeve 6 and engaging the base section 95a of said rod 95. As 35 illustrated, the spring 98 is supported by the upper end of the motor shaft 5 and, if desired, a reduced extension 5a of the latter may be received interiorly of the spring convolutions.

As stated, the sleeve 6 is rotatable with the 40 motor shaft 5. The upper extension 6a of sleeve 6 together with the fingers 6b and enlarged sections 6c thereof, likewise, are rotatable with the motor shaft 5. The rod 95, due to the driving connection effected by pin 96, is rotatable with 45 the sleeve 6. At the same time, said rod 95, due to the aligned slots in sleeve 6 is movable, to a limited extent, interiorly of said sleeve 6, its extension 6a and the fingers 6b.

The turntable T, as illustrated particularly in 50 Fig. 6, rests directly upon and is supported by the flange 99a of a sleeve 99, said turntable, flange 99a and sleeve 99 being rotatable together as a unit. The sleeve 99 is freely slidable upon the extension 6a of sleeve 6 to which said sleeve 99 55 is connected for rotation therewith in any suitable manner. To this end, the exterior surface of the aforesaid extension 6a may be of polygonal configuration in cross-section and the interior surface of sleeve 99 of similar polygonal 60 configuration in cross-section. The flanged section between the sleeve 6 and its upper extension 6a forms a stop limiting downward movement of the sleeve 99.

Referring particularly to Figs. 5 and 6, the 65 aforesaid sleeve 99 is shown as carrying a ring 100 which is rotatable therewith. Ring 100, preferably in connection with anti-friction members 101, is supported by a non-rotatable ring 102, in turn, supported by a non-rotatable supporting member 103. The latter is swiveled interiorly of a ring 104 and, for this purpose, there may be utilized diametrically aligned screws 105 threaded into said ring 104 and having stems loosely re- 70 75

ceived in diametrically aligned openings in the member 103, Fig. 5.

The ring 104, in turn, is swiveled in a non-rotatable supporting member which, in the example shown comprises arms 106 integral with each other and angularly related as shown particularly in Fig. 5. For thus swiveling the ring 104, there may be utilized screws 107 aligned diametrically of said ring 104 and threaded into a circumferentially complete section 108 formed by said arms 106, 106 where they are joined together, said screws 107 having stems loosely received in perforations in the ring 104.

The construction comprising the ring 102, member 103, ring 104 and the section 108 forms a universal joint and, to the end that true universal action may exist, a line including the screws 105 should be disposed at right angles to a line including the screws 107.

Carried by the upper surface of frame member 1 is a bracket having upstanding parallel arms 109, 109, Figs. 2, 3 and 5, each arm having an elongated slot 109a disposed substantially parallel with the frame member 1. Slidable in the slots 109a and guided thereby is a rod or member 110 carried closely adjacent the end of that arm 106 to the left, Figs. 2, 3 and 5.

Said last named arm 106 has pivoted thereto one end of a link or member 111, the other end of which is pivoted to an arm 112 upstanding from the frame member 1 and carried thereby. As illustrated particularly in Figs. 2 and 3, a pair of the links 111 are thus utilized and they are pivoted to opposite sides of that arm 106 to which reference has just previously been made.

As illustrated particularly in Fig. 5, that arm 106 to the right has pivoted thereto one end of a link 113, the other end of which is pivoted to one end of a lever 114, the other end of which is suitably secured to a shaft 115 for movement therewith. As illustrated in Figs. 9 and 12, the shaft 115 is mounted in bearings formed in the aforesaid depending section 1b of frame member 1 and in another depending section 1e of said frame member 1. Secured to the shaft 115 for movement therewith is a ratchet member 116 beyond which, on said shaft 115, is loosely mounted one end of a lever 117, the other end of which carries a cam roller 118 coactable with the aforesaid cam K4.

Pivoted to the lever 117 on a member 119, Figs. 13 and 14, is a pawl 120 utilizable for imparting motion to the aforesaid ratchet 116, said pawl 120 being suitably biased into engagement with the serrated face of ratchet member 116, as by a spring 121, one end of which is connected to said pawl 120 and the other end of which is connected to a lug projecting from the lever 117. A second spring 122 is connected at one end to said lever 117 and at its other end to a pin 123 projecting from the depending section 1b of frame member 1. Spring 122 maintains the roller 118 in engagement with cam K4 and, obviously, should be of greater power than the spring 121. Pawl 120 has a tail section 120a utilizable as hereinafter described. Said pawl 120 also comprises a laterally projecting pin 124 utilizable as hereinafter described.

As illustrated particularly in Fig. 14, a pair of holding pawls 125 and 126 are pivoted on a pin which is carried by a lug 127 projecting from the depending section 1b of frame member 1. The pawls 125 and 126 are suitably biased into engagement with the serrated face of ratchet member 116, as by a leaf spring 128 secured to a lug

projecting from the depending section 1b of frame member 1 and having separate upper sections engaging the respective pawls 125 and 126. A pin 129 projecting laterally from and carried by the pawl 125 extends through an elongated slot 130 of pawl 126. Said pin 129 is actuated as hereinafter described to release all of the aforesaid pawls from the ratchet member 116.

As soon as the cycle of automatic operation is initiated, the cam K4 starts to move in a counter-clockwise direction, Fig. 13, and, within a brief period, the high area thereof engages the roller 118 to move the lever 117 in a counter-clockwise direction, Fig. 13 and storing energy in the spring 122. Spring 121, however, holds the pawl 120 in engagement with the ratchet 116 and, the ratchet member 116 is swung in a counter-clockwise direction, Fig. 13, due to the fact that said pawl 120 is pivoted to the lever 117. As a result, shaft 115 is moved in a similar direction 20 as is the lever 114, Figs. 5, 13 and 15, to thereby elevate the link 113.

When the link 113 is thus elevated, the lower end of arm 106 to the right, Fig. 5 is similarly elevated, as are the screws 107, 107 of arms 106, 25 106, the lower end of arm 106 to the left, Fig. 5, sliding in a horizontal plane due to the control exercised thereon by member 110 in conjunction with the slots 109a of arms 109. Links 111 cause straight line movement of the screws 107 and 30 preventing side friction between the sleeve 99 and extension 6a of sleeve 6.

The ring 104 is elevated with the screws 107, 107 but is not tilted with the arms 106, 106 due to the restraining influence of the extension 6a 35 of sleeve 6 and further due to the fact that said ring 104 is swiveled on said arms 106, 106 whereby the weight of the turntable T and the thereby-carried records R contributes to the prevention of tilting action.

Movable upwardly with the ring 104 are the screws 105, member 103, ring 102, the anti-friction members 101, rotatable ring 100, rotatable sleeve 99, the turntable T and the thereby-carried records R. The turntable T and the records R 45 thereon, of course, continue rotating before, during and after occurrence of the above described action.

As the turntable T is thus moved upwardly, the sleeve 99 slides on the upper extension 6a of 50 sleeve 6, the latter, together with the fingers 6b and enlarged sections 6c thereof rotating with the motor shaft but not partaking of upward movement.

As clearly appears on the drawings, the records 55 R are disposed in threaded relation on the aforesaid fingers 6b in the sense that each record has been passed flatwise toward the turntable T, said fingers 6b or their enlarged sections 6c extending through the record center perforation. During any period of sound reproduction, the parts are positioned as shown in Figs. 5 and 6. When thus positioned, the records are gripped at their respective center perforations due to the fact that rod 95 is biased upwardly, Figs. 5 and 6, by 65 spring 98, said rod 95 thereby maintaining the ball 94 in engagement with the enlarged sections 6c of fingers 6b. The latter, accordingly, are spread apart and so held under the force of spring 98. As a result, each record R is positively 70 gripped for rotation with the turntable T.

Accordingly, as the turntable T is moved upwardly or elevated under the influence of cam K4 as described above, the entire group of records R slide upwardly with respect to the fingers 75

6b and their enlarged sections 6c. Eventually, the topmost record R is moved entirely beyond the upper extremities of said enlarged sections 6c and thus is freed from the turntable T or associated rotating parts.

Prior to this time and as described above, the sound box S and stylus s have been elevated well above said topmost record R. Likewise, the member 71, at its rim 71a, has previously been moved 10 into engagement with the periphery of said topmost record R. Furthermore, the cam K controlling movement of member 71 as just described has moved, at this time, to a position wherein its cam surface is spaced from the roller 54. The 15 spring 55, Fig. 3, with considerable force, is tending to move said roller 54 into engagement with cam K, but this action has not occurred because movement of member 71 has been prevented by said topmost record R which has been gripped at 20 its center by the aforesaid enlarged sections 6c of fingers 6b. Member 71, as hereinbefore described, is mechanically connected to the aforesaid lever 53.

However, when said topmost record R is moved 25 upwardly beyond said enlarged sections 6c of fingers 6b, the member 71 is no longer held under restraint and, accordingly, said member 71, under the influence of spring 55, suddenly resumes movement in a counter-clockwise direction, Fig. 30 1, and snaps said topmost record R from right to left, Fig. 1, to a region at one side of the turntable T.

Counter-clockwise movement, as aforesaid, of member 71 is discontinued when the cam roller 35 54 returns to the surface of cam K. As herein-after described, cam K, in connection with the mechanism controlled thereby, further functions before the cycle of automatic operation is concluded.

40 As described above, the cam K4, roller 118, lever 119 and pawl 120 cooperate to move the ratchet member 116 in a counter-clockwise direction, Fig. 13, to elevate the turntable T. As the topmost record R is freed from the enlarged section 6b of fingers 6c, the member 71 suddenly moves counter-clockwise, Fig. 1, as described above. The shaft 58 is in the train of mechanism between member 71 and lever 53 and, therefore, in response to the last named movement of member 71, the shaft 58 is suddenly moved counter-clockwise, Fig. 12. As a result, arm 67 is similarly swung, Fig. 12, to move the lever 69 clockwise, Fig. 12. The latter, adjacent its free end, snaps against the tail section 120a 50 of pawl 120 to swing the latter in a clockwise direction, Fig. 13, and disengages the same from ratchet member 116. Accordingly, further movement of cam K4 during that particular cycle is without effect in further elevating the turntable 55 T since lever 69 holds the pawl 120 disengaged from ratchet member 116 until after the highest area of cam K4 has passed in a counter-clockwise direction, Fig. 13, beyond the cam roller 118.

60 As the ratchet member 116 is moved in counter-clockwise direction, Fig. 13, to elevate the turntable T, the ratchet teeth idle past the holding pawls 125 and 126. However, when the last named counter-clockwise movement of ratchet member 116 was discontinued as just described, one or the other of said holding pawls 125 and 70 126 exercise a clutching effect on said ratchet member 116 and prevent clockwise movement, Fig. 13, of the latter under the weight of the turntable and the records thereon. In this manner, the turntable T is held in the position to

which elevated at the time the topmost record is discharged therefrom.

It will be observed that the edged surfaces of pawls 125 and 126 are staggered, Figs. 13 and 14. By virtue of this construction, any substantial clockwise movement, Fig. 13, is prevented of ratchet member 116 after the aforesaid elevating pawl is detached therefrom.

Manual control of turntable T

10 A gear segment 131 loosely mounted on the aforesaid shaft 115 comprises an elongated slot 131a in which is received a pin 132 projecting laterally from the aforesaid ratchet member 116.

Gear segment 131 meshes with another gear 15 segment 133 loosely pivoted on a member 134 projecting from the depending section 1b of frame member 1, said gear segment 133 being suitably spaced from said depending section 1b by a hub 135 through which the member 134 extends, 20 Fig. 3.

The gear segment 133 comprises a handle section 133a extending upwardly through a slot in the motor board m, Fig. 1, and through a plate 133b having an elongated slot, the slot wall 133c 25 limiting clockwise movement, Fig. 4, of handle section 133a. At its upper end, the handle section 133a is fashioned to form a hollow passage slidably receiving a member 136 from which depends a rod or stem 137 having an angular end 30 137a. Rod 137 is slidable in bearings 138 projecting from said handle section 133a. Between the upper bearing 138, Figs. 4 and 13, and a collar 139 carried by and movable with rod 137 a spring 140 is coiled around said rod 137 for 35 biasing the latter upwardly, Figs. 4 and 13, to an extent determined by a collar 142 carried by and movable with said rod 137.

The angular end 137a of rod 137 extends into and through an arcuate slot 143a of an arm 143 40 having a cam face 143b, Figs. 13 and 14, coactable with the aforesaid pin 129 which, as stated, extends from the pawl 125. Lever 143 is pivoted on and movable with a shaft or member 144 journaled in the depending sections 1b and 1e 45 of frame member 1, Fig. 12.

When a cycle of automatic operation is initiated, the ratchet member 116 is moved in a counter-clockwise direction, Fig. 13, as described. Pin 132 moves with the ratchet member 116 50 and, when the end of slot 131a is reached, the gear segment 131 is connected to said ratchet member 116 and moves therewith. As a result of such movement of gear segment 131, the gear segment 133 is moved in a clockwise direction, 55 Fig. 13, the angular end 137a of rod 137 moving, to a slight degree, from left to right, Fig. 13, without effect on the lever 143.

For each cycle of automatic operation, the gear segment 133 is thus given a step of movement in 60 a clockwise direction, Fig. 13.

Finally, after all of the records R, or all save the lowermost, have been discharged from the turntable T, the handle section 133a will have been moved closely adjacent the stop wall 133c 65 of member 133b, Fig. 4. The latter may now be grasped in one hand and the member 136 depressed by thumb pressure, if desired. As a result, the rod 137 is moved downwardly and the lever 143 moved in a clockwise direction, Fig. 13. 70 When lever 143 is thus moved, the cam face 143b thereof engages the pin 129 and moves the same from left to right, Fig. 13. Accordingly, pawl 125 is disengaged from the ratchet member 116. The pin 129 coacts with the wall of slot 130 to 75

disengage pawl 126 from said ratchet member 116 and the pawl 125 coacts with the pin 124 extending laterally from pawl 120 to disengage the latter from said ratchet member 116. Thus, 5 all of the pawls are disengaged from the ratchet member 116 and, while the member 136 is maintained in its depressed position, the handle section 133a may be moved to lower the turntable T. By so doing, motion is transmitted from the gear segment 133 to the gear segment 131 and from the latter to the ratchet member 116, from 10 which motion is transmitted to the sleeve 99 through the chain of mechanism hereinbefore described.

15 When the pressure on member 136 is released, the rod 137 moves to its upper position under the influence of spring 140, and carries the arm 143 to its non-operative position. As a result, all of the pawls, under the influence 20 of their respective springs are returned to co-acting relation with the ratchet member 116.

Obviously, the aforesaid handle section 133a may be actuated, if desired, at times other than when the turntable T is in its uppermost position. 25 Under such circumstances, movement of said handle section 133a in the proper direction causes the turntable to be either raised or lowered as desired.

30 *Mechanism effecting lateral movement of the sound box S*

As hereinbefore described and as illustrated particularly in Fig. 10, a collar 64 is freely oscillatable on the member 22. This collar 64 has an extension arm 63 connected, as described above, 35 to the oscillatory shaft 58 of the record discharge or ejector mechanism.

As illustrated particularly in Figs. 2, 3 and 12, the aforesaid collar 64 comprises another extension arm 145 movable therewith and carrying 40 clutch or locking mechanism utilizable for effecting lateral movement of the sound box S both from and toward the turntable center.

As shown on the drawings, particularly in Figs. 45 16, 17, 18, and 19, the aforesaid clutch mechanism comprises levers 146 and 147 movable with respect to each other and pivoted on an arm 148 formed integrally with the arm 145. Any one of a number of suitable arrangements may be utilized in accordance with this general plan. As shown, a single screw 149 is utilized for pivoting the levers 146 and 147 on the arm 148.

Pivoted to the lever 148 is a latching lever 150 suitably biased in a clockwise direction, Figs. 55 16-19, as by a helical spring 151 connected to the upper end thereof and to an upstanding section 147a of the lever 147, clockwise movement, Figs. 16-19, of said lever 150 being limited by a lug 148a projecting from the arm 148. Lever 150 60 comprises a ledge section 150a and an angularly projecting section 150b both utilizable as herein-after described.

Lever 146 is pivoted for movement in a different plane from that occupied by the lever 150 65 and comprises a laterally projecting section 146a coactable with the aforesaid ledge section 150a of lever 150. Lever 146 is suitably biased in a counter-clockwise direction, Figs. 16-19, as by a helical spring 152 connected to an upper extension thereof and to a lug projecting upwardly from arm 148, counter-clockwise movement, Figs. 16-19 of lever 146 being limited by engagement effected by a laterally projecting section 146b thereof with the adjacent surface of arm 148,

Fig. 19. Lever 146 comprises a depending section 146c terminating in a laterally projecting section 146d utilizable as hereinafter described. The end of lever 146 is curved as indicated at 146c for a purpose later to be described.

Lever 147 comprises a hook-shaped end 147b and a laterally projecting section 147c coactable with the adjacent surface of arm 148 whereby counter-clockwise movement, Figs. 16 and 19, of said lever 147 is limited. The end of lever 147 10 comprises a sloping or inclined face 147d utilizable for a purpose later to be described.

Upstanding from the frame member 1 is a member 153 having a screw 154 adjustable therein and threaded therethrough, Fig. 3. Screw 154, 15 at its non-headed end, is coactable with the angularly projecting section 150b of lever 150, as hereinafter described.

Depending from the frame member 1 is a member 155 having a screw 156 adjustable therein 20 and threaded therethrough, Fig. 5. Screw 156, at its non-headed end, is coactable with the laterally projecting section 146d of lever 146, as hereinafter described.

The normal positions of the parts of the here- 25 before described clutch mechanism with respect to each other during any period of sound reproduction is as illustrated in Fig. 16 although, at such times, said clutch mechanism parts may be differently positioned with respect to the 30 screws 154 and 156.

As hereinbefore described, the spring 55 in response to movement of cam K, as soon as a cycle of automatic operation is initiated, moves the shaft 58 about its longitudinal axis to swing the 35 rod 73 in a counter-clockwise direction, Fig. 1. This movement of shaft 58 causes counter-clockwise movement of lever 59, Fig. 12, such motion being transmitted by the link 60 to the lever 61 which coacts with the non-headed end of 40 screw 65 to move the collar 64 in a counter-clockwise direction, Fig. 12. Arm 145 forms a part of collar 64 and, therefore, the clutch mechanism parts carried thereby move along a circular path and in step with the rod 73 as the latter 45 swings in a counter-clockwise direction, Fig. 1.

Very soon after the cycle of automatic operation is initiated, the sound box S is elevated as hereinbefore described under the control of cam K3. In so doing, the horizontal section 33c of 50 member 33 is elevated into the path of lever 147 which, and other parts of the last described clutch mechanism, is moving from right to left, Fig. 16 under the influence of spring 55. During continued movement of lever 147 as just described, 55 the sloping face 147d thereof engages the aforesaid horizontal section 33c, the latter causing momentary elevation of said lever 147 which quickly snaps downward, under the influence of spring 151, into engagement with said horizontal 60 section 33c after the hook-shaped end 147b of lever 147 has passed therebeyond.

The clutch mechanism moves as the rod 73 moves and comes into the position illustrated in 65 Fig. 17 after the topmost record R has been released from the turntable T the lower surface of lever 147 sliding over the upper surface of section 33c. In this position, the angular section 150b of lever 150 has been moved into engagement with the screw 154 to swing said lever 70 150 in a counter-clockwise direction, Fig. 17, and to disengage the ledge section 150a of said lever 150 from the lateral section 146a of lever 146. As a result, the lower surface of lever 146, under 75

the influence of spring 152, comes into engagement with the upper surface of section 33c. When the rod 73 starts moving in a clockwise direction, Fig. 1, under the direct influence of cam K, the lever 59 moves in the same direction, Fig. 12, motion of said lever 59 being transmitted to the lever 61 through the link 60. The lever 61 in conjunction with spring 66 transmits such motion to the collar 64 which is thereby caused to move in a counter-clockwise direction, Fig. 12. In this connection, it should be noted that the spring 66 does not expand during such action since it is of relatively great strength and is utilizable in connection with lever 61 and screw 65 for adjusting the effective length of link 60.

Accordingly, the clutch parts are moved from left to right, Fig. 17. In so doing, the angular section 150b of lever 150 retreats from the screw 154 and said lever 150, under the influence of spring 151, eventually assumes its normal position, namely, that occupied thereby while in engagement with the lug 148a of arm 148. Furthermore, the lower surfaces of levers 146 and 147 move along the upper surface of section 33c until the hook-shaped end 147b of lever 147 engages said section 33c. At this time, the lever 146, under the influence of spring 152, moves counter-clockwise from the position shown in Fig. 17 to a limited degree, the curved end 146e of said lever 146 coacting with the section 33c to maintain said lever 146 in the position shown in Fig. 18.

The section 33c is now temporarily locked to the above described clutch mechanism and is movable therewith in both directions. It follows, therefore, that the parts controlled by said section 33c are similarly movable with said clutch mechanism. These parts include the rack member 35, the member 27, tone arm 29 and sound box S.

The aforesaid section 33c is thus locked to the clutch mechanism while the latter is moving from left to right, Figs. 17 and 18. The cam K is so designed and the arrangement of the parts is such that, due to the above described locking action, the sound box S is moved laterally from the turntable center to a position where the sound box stylus s is without the periphery of the topmost record R on the turntable, no matter whether the diameter of that record is ten or twelve inches. At this time, however, the movement of the clutch parts is not of sufficient extent to bring the lateral section 146d of lever 146 into engagement with the screw 156.

Thereafter, during continued movement of the cam K, the spring 55 becomes effective to again swing the rod 73 in a counter-clockwise direction, Fig. 1, until the member 75 engages the periphery of the now topmost record R on the turntable T, this being the record from which sound is next to be reproduced. The clutch parts move with the rod 73 and so does the section 33c together with the other parts movable with the latter including the sound box S since the aforesaid locking action still persists. The arrangement is such that when the member 75 engages the periphery of the topmost record R as last described the sound box S has moved toward the turntable center and its stylus s is positioned directly above a point just within the periphery of said last named topmost record and just without the spiral sound reproducing groove structure thereof. The sound box remains in the 75 position last described for a brief interval but

very soon, in response to the control of cam K3, said sound box is lowered, the section 33c moving from between the hook-shaped end 147b of lever 147 and the curved end 146c of lever 146. When this happens, counter-clockwise movement of both levers 146 and 147 under the influence of the respective springs 152 and 151 is prevented due to engagement of the lugs 146b and 147c with adjacent surfaces of the arm 148.

Soon thereafter, the next period of sound re-production is initiated as hereinafter described, but, before this happens, the cam K3 again swings arm 73 in a clockwise direction, Fig. 1, to cause the lateral section 146d of lever 146 to engage the screw 156. As a result, the lever 146 is swung clockwise, Fig. 19, and the lateral section 146a thereof is reengaged with the ledge 150a of lever 150. The respective clutch parts, accordingly, resume the position shown in Fig. 16.

Switch mechanism

Referring particularly to Fig. 3, the upper surface of frame member 1 is shown as carrying suitably supported members or plates 157 and 157a. These plates are formed of suitable insulating material and are spaced for the reception of a block 158 of insulating material, to opposite sides of which the respective conductive members 159 and 160 are secured. Conductors 161 secured, respectively, to the members 159 and 160 lead to the coil structure of the aforesaid motive device M. The conductive member 159 terminates in a resilient section 159a having a laterally projecting contact member coactable with a similar contact member projecting from a resilient conductive member 162 electrically associated with the aforesaid conductive member 160. Pivoted between the plates 157 and 157a on a member 163 is a dog or actuating member 164 having a nose 164a coactable with the tip of member 162 to separate the aforesaid contact members. Switch mechanism of the character just described is satisfactory in operation; it shall be understood, however, that switch mechanism of any other suitable type may be utilized as desired.

Coactable with the dog 164 is a lug 165a formed intermediate of the ends of an arm 165b of a lever 165 spaced above the aforesaid lever 45 and pivoted on the same member 46 to which the last mentioned lever is pivoted. Arm 165b of lever 165, at its free end, comprises a depending section 165c, Figs. 7 and 8, coactable with the afore-said pin 12 carried by clutch crescent 10.

Connected to the arm 165b of lever 165 is one end of a link 166, Figs. 7 and 8, the other end of which is pivoted to a U-shaped member 167, opposite arms 167a, 167a of which are pivoted at 168 to the arms of a supporting bracket 169 having a base section 169a carried by the frame member 1. The arms 167a, 167a of member 167 are coactable at their ends with the aforesaid ring 97 which, as stated, is connected to and movable with the base section 95a of rod 95.

Another arm 165d of lever 165 comprises a depending section 165e coactable with the end of the aforesaid lever 43.

Another arm 165f of lever 165 comprises an enlarged section 165g coactable with the end of a switch-operating lever, as hereinafter described.

Another arm 165h of lever 165 comprises a projecting lug to which is connected one end of a helical spring 170, the other end of which is connected to a post 171 upstanding from the frame 75

member 1. Spring 170 biases lever 165 in a clockwise direction, Fig. 3. It shall be understood, however, that any other suitable arrangement may be utilized for biasing said lever 165 in the direction named.

The aforesaid arm 165h of lever 165 comprises a depending pin 165i coactable with the cam surface 172a of a disk 172 pivoted on a member 173 upstanding from the frame member 1. A pin 174 upstanding from said frame member 1 serves to limit oscillatory movement of disk 172 because coactable with spaced lugs or projections 172b and 172c thereof.

Pivoted to the disk 172 on a member 175 is a lever 176 having a nose coactable with the adjacent end of arm 165h of lever 165. Lever 176 has one end of a helical spring 177 connected to a lug upstanding therefrom, the other end of said spring 177 being connected to the aforesaid post 171. Lever 176 comprises an arm from which depends a flange 176a utilizable as herein-after described. Lever 176 also comprises an extension 176b adapted for manual operation.

With the parts positioned as illustrated in Fig. 3, the contact members carried by the respective conductive members 159 and 162 are in engagement and the motive device M is in operation.

If the extension 176b is now swung, as by a manual act, in a counter-clockwise direction, Fig. 3, the nose of lever 176 is disengaged from the end of the arm 165h of the lever 165. When this happens, spring 177 becomes effective to swing the disk 172 in a counter-clockwise direction, Fig. 3, the lever 176 being carried by said disk 172 when it thus moves, and such movement being discontinued when lug 172b engages pin 174. In response to such movement of disk 172, the cam surface 172a thereof, by coaction with the pin 165i, swings the lever 165 in a counter-clockwise direction, Fig. 3, thereby storing energy in the spring 170.

As a result, the nose 165a of lever arm 165b swings the dog 164 in a clockwise direction, Fig. 3, the dog nose 164a engaging the tip of the conductive member 162 to separate the contact member carried thereby from the adjacent contact member. In this manner, operation of the motive device M is discontinued.

Counter-clockwise movement, Fig. 3, of lever 165 as just described positions the depending section 165c of lever arm 165b in the path of the upstanding pin 12 carried by the clutch crescent 10. Under such circumstances, said clutch crescent 10 may not be moved to a position where its tooth 10a engages the clutch wheel 1 even though the lever arm 45c should be moved in a counter-clockwise direction, Figs. 3 and 7. It results, therefore, after the contact members are opened that the operation of the mechanism may not be initiated when the motor M is stopped since, for the reason just stated, it is impossible to "trip" the clutch mechanism when the switch contact members are open.

Counter-clockwise movement, Fig. 3, of lever 165 as just described, by movement of link 166, causes the arms 167a, 167a of member 167 to engage and depress the ring 97, Figs. 6 and 8. This result follows because the spring 177 controlling movement of lever 165 is of greater strength than the spring 98 controlling elevation of ring 97. Accordingly, the rod 95 is depressed whereby the fingers 6b may be moved toward each other to permit ready disposition of the desired number of records on the turntable T. When the lever 165 is moved to place the motive device M in op-

eration, the pressure on ring 97 is released and the spring 98 elevates the rod 95 which, with the ball 94 spreads the fingers 6b and causes the records to be gripped at their center perforations.

To close the aforesaid switch contact members, the extension 176b of lever 172 is swung in a direction the reverse of that described above. As a result, the disk 172 retraces its path and under the influence of spring 170, the lever 165 returns to the position shown in Fig. 3. Accordingly, the switch contact members are closed because of the inherent resiliency of the conductive members carrying them; furthermore, the depending section 165c of lever arm 165b is removed from the path of the pin 12 carried by clutch crescent 10. The nose of lever 176 is held in engagement with the adjacent end of lever arm 165h by the spring 177, clockwise movement, Fig. 3, of disk 172 beyond the position illustrated in Fig. 3 being limited by engagement effected between the lug 172c of disk 172 and the pin 174, the latter also serving to limit clockwise movement, Fig. 3, of lever 176.

Miscellaneous features and selective control mechanism 25

As hereinbefore described, the lever 37 has the levers 43 and 44 pivoted thereto in suitable spaced relation.

One arm 44a of lever 44 comprises a sloping 30 surface 44b terminating in a ledge section 44c. Opposite ends of a helical spring 178 are connected, respectively, to lugs or projections upstanding from the respective levers 43 and 44. Lever 37 has a lug 179 upstanding therefrom, said 35 lug 179 serving to limit clockwise movement, Fig. 3, of lever 43. Lever 43 comprises a nose 43a disposed, during automatic operation of the mechanism, on the ledge section 44c of lever 44, the levers 43 and 44 being retained, during 40 automatic operation, in the position shown in Fig. 3 by the locking action thus effected and by the spring 178.

The other arm 44d of lever 44 terminates in an upturned cam surface 44e coactable with which 45 is the end of a screw 180 adjustable in a bracket 181 carried by the aforesaid link 113 which, as described, serves to transmit motion from the cam K4 for elevating the turntable T. As illustrated particularly in Fig. 3, the frame member 50 I comprises an opening 182 through which the link 113, the end of lever 114, screw 180 and bracket 181 are movable.

Referring particularly to Figs. 5, 9 and 15, the screw 180 is moved step-by-step along a curved 55 path toward the cam surface 44e of lever 44 during succeeding steps of elevation applied to the turntable T. Finally, during that cycle of automatic operation when the last or lowermost record R is being elevated to sound reproducing position, 60 the upper end of screw 180 comes to a predetermined level where it has substantially moved said cam surface 44e to thereby swing lever 44 in a counter-clockwise direction, Fig. 3, provided that said lowermost record R is not unduly thick 65 or warped as hereinafter described. As a result, lever 44 is disengaged from the nose 43a of lever 43 to thereby permit the latter to swing in a clockwise direction Fig. 3, into engagement with lug 179 of lever 37, the nose 43a of lever 43 70 coming to rest in a position where it engages the sloping surface 44b of lever 44. By so doing, the end of lever 43 to the left is disposed in a position where it is coactable, not with the lug 45a of lever 45, but with the depending flange 165e of 75

lever 165. Accordingly, when the sound box stylus *s* moves into the eccentric groove *e* of the last or lowermost record *R* on the turntable *T*, movement of lever 37 in a clockwise direction, Fig. 3, follows as hereinbefore. However, in response to such movement and differing from the operation heretofore described, the lever 165, and not the lever 45, is swung counter-clockwise, Fig. 3. As a result of such movement of lever 165, 10 the switch contact members are opened and operation of the motive device *M* is discontinued. When the switch contact members are thus opened, the end of lever 165*h* is disengaged from the adjacent nose of lever 176, the latter moving 15 counter-clockwise, Fig. 3, under the influence of spring 177. Accordingly, when the motive device *M* is again to be placed in operation, the lever 176 must be actuated in reverse direction. In moving into the position last described the 20 automatic mechanism, with the exception of the eccentric groove control mechanism per se, is placed in non-operative condition, and therefore, the herein described talking machine or phonograph mechanism is placed in condition for non- 25 automatic or manual operation. That is, the sound box *S* may be manually elevated from said last or lowermost record, the latter manually removed from the turntable, a new record substituted therefor on the turntable, the sound box 30 placed in starting position, and the motive device *M* placed in operation by movement of the lever handle 176*b*. After sound has been reproduced from the record thus placed in position, the operation is as before stated, namely, 35 discontinuation of operation of the motive device *M*. Obviously, the foregoing may be repeated as desired to successively reproduce sound by manual operation of the records in contra-distinction to automatic operation.

40 With the turntable *T* in its lowermost position, the sleeve 99 rests upon the flanged surface of sleeve 6, Figs. 5 and 6. At this time, the handle extension 133*a* is in engagement with the slot wall 133*d* of plate 133*b*, Figs. 1 and 4. Furthermore, at this time the pin 132 is in the upper 45 end of slot 131*a* as shown in Fig. 13. With said turntable *T* in its lowermost position as just stated, the turntable stem, namely, the fingers 6*b* and their extensions 6*c* disposed above said 50 turntable *T*, is of a length sufficient to accommodate twelve commercial records of normal thickness, although the length of said stem above the turntable *T* may be different to receive a different 55 number of records if desired.

55 After the first period of sound reproduction, namely, that period which is effected from the topmost record *R* on the turntable *T* when the latter is in lowermost position, a period of automatic operation ensues at which time the cam 60 K4 swings the ratchet member 116 in a counter-clockwise direction, Fig. 13, the pin 132 moving toward but not quite reaching the lower end of slot 131*a*. Accordingly, during the first period of automatic operation, there is no movement of 65 the gear segments 131 and 133, or of the handle extension 133*a*.

In a manner as hereinbefore described, the 70 period of automatic operation to which reference has just been made causes the discharge from above the turntable *T* of said last named topmost record *R* and initiates a second period of sound reproduction from the next lowermost record *R* on said turntable *T*.

75 After the second period of sound reproduction, a second period of automatic operation ensues

at which time the cam K4 further swings the ratchet member 116 in a counter-clockwise direction, Fig. 13, the pin 132 almost immediately reaching the lower end of slot 131*a* and there remaining to thereafter cause movement of the gear segments 131 and 133 accompanied by clockwise movement, Fig. 13, of handle extension 133*a* in response to any counter-clockwise movement, Fig. 13, of ratchet member 116. In this manner, the ratchet member 116 is caused to "lead" the 10 handle extension 133*a*.

During succeeding periods of automatic operation, the ratchet member 116 and gear segment 131 thus move with each other, motion being transferred from ratchet member 116 to the gear segment 131 by the pin 132 which, as stated, remains at the lower end of the slot 131*a*.

If all of the records *R* are of normal thickness, elevation of said turntable *T* to effect removal of the second record *R* from the bottom of the 20 group of records brings the screw 180 to the aforesaid predetermined level where it engages and causes sufficient movement of cam surface 44*e* of lever 44 to thereby effect movement of lever 43 to the position where it is coactable 25 with the depending flange 165*e* of lever 165. Accordingly, after sound has been reproduced from the lowermost record *R*, the control exercised by the eccentric groove *e* thereof causes the lever 165 to be moved counter-clockwise, Figs. 2 and 3, 30 to thereby open the switch contact members and discontinue operation of the motive device *M*. This is the normal and intended operation, the lowermost record *R* remaining on the turntable *T*. Under such circumstances, the handle extension 35 133*a* is spaced from the slot wall 133*c* of plate 133*b* a distance slightly greater than the distance through which said handle extension 133*a* is moved while the turntable *T* is being elevated a distance equal to the thickness of a normal record.

Should it happen that the lowermost record *R* on the turntable *T* is of greater thickness than usual or should it be warped to produce that effect, it may happen that the turntable *T*, when 45 moved upwardly to effect the discharge of the record *R* immediately above said lowermost record, is not elevated sufficiently to cause, by screw 180, enough movement of cam surface 44*e* of lever 44 to produce the above described movement of lever 43 where it is coactable with the depending flange 165*e* of lever 165. Accordingly, after sound has been reproduced from the lowermost record *R*, the control exercised by the eccentric groove *e* thereof causes the lever 45, and 55 not the lever 165, to be swung counter-clockwise, Figs. 2 and 3. As a result, under the conditions stated, a period of automatic operation ensues after sound has been reproduced from said lowermost record *R*. Therefore, all of the usual 60 automatic operations are again effected, the turntable *T* being elevated, the lowermost record *R* removed therefrom by rod 73, and the sound box *S* controlled in the customary manner.

When the turntable *T* is elevated as last described, the screw 180 immediately partakes of sufficient upward movement to move cam surface 44*e* of lever 44 to a sufficient extent to thereby produce the desired movement of lever 43 to a position where it is coactable with the depending 70 flange 165*e* of lever 165. Furthermore, elevation of said turntable *T*, as last described, causes movement of handle extension 133*a* into close proximity with the slot wall 133*c* of plate 133*b*.

Thus, when the lowermost record *R* is abnormal 75

as described above, operation of the motive device M is not discontinued at the conclusion of the period of sound reproduction therefrom but, instead, another cycle of automatic operation is initiated. This makes it necessary to provide an arrangement for controlling movement of the sound box S during said last named cycle of operation and for discontinuing operation of the motive device M.

To this end, a turntable T₁ of the character illustrated in Figs. 5a and 5b may be utilized in lieu of the hereinbefore described turntable T which, as illustrated in Figs. 5 and 6, is slightly dished and covered with a layer of felt or the like.

The turntable T₁ likewise, may be dished for the reception of a disk R₁ formed, preferably, from the same kind of material as are the records R. Disk R₁ is provided with a center perforation for the reception of the turntable stem and comprises a spiral groove 211 of relatively great pitch which terminates in a groove or circle e₁ eccentrically disposed with respect to the center perforation of said disk R₁. Disk R₁ may be adhesively or otherwise suitably secured to the turntable T₁ which should be rounded or curved on its periphery as indicated at 212.

With a turntable T₁ utilized in lieu of the turntable T, the operation during and subsequent to the cycle of automatic operation following the period of sound reproduction from the last or lowermost record R on the turntable T₁ is as follows:

After the eccentric groove e on said lowermost record R exercises its control function, the sound box S is elevated and the rod 73 swings counter-clockwise, Fig. 1. No records are on said turntable T₁, to impede swinging movement of said rod 73, the turntable T₁ also being ineffective to discontinue movement of rod 73 because the member 75 rides freely over the curved edge 212 of said turntable T₁.

Therefore, rod 73 operates substantially as during the hereinafter described repeating operation, and by lever 69, causes disengagement of the pawl 120 from ratchet 116 before there has been any elevation of said turntable T₁.

The sound box S is moved first from the center of turntable T₁ and then toward the center thereof, the same as hereinbefore described in connection with Figs. 16-19. Since rod 73 is not impeded either by a record R or by the turntable T₁ as it moves towards the center of the latter on its second excursion, it results that the sound box stylus s is positioned above a point well within the periphery of the disk R₁. From this position, said stylus s is lowered into contact with said disk R₁ just prior to the conclusion of the cycle of automatic operation.

The stylus s, when lowered, quickly drops into the spiral groove 211 of said disk R₁ which causes rapid movement thereof toward and into the eccentric groove e₁ which functions the same as any record groove e to cause clockwise movement, Figs. 2 and 3, of lever 31 whereby lever 43 causes the lever 165 to swing counter-clockwise, Figs. 2 and 3, to thereby discontinue operation of the motive device M.

In this manner, operation of the motive device M is discontinued either after the period of sound reproduction from the second record from the bottom of the group of records or from the lowermost of said group of records. In the first case, the turntable T₁ is elevated to less extent than

in the latter, but, in either position is adopted for non-automatic or manual operation.

When the member 136 is depressed, the arm 143 is swung clockwise, Fig. 13, to release all of the pawls from ratchet 116. As soon as this happens, 5 the handle extension 133a may be moved toward and into engagement with the slot wall 133d of plate 133b. This action places the slot 131a in a predetermined position and, when the turntable T₁ is in its lowermost position as defined by the 10 flanged surface of sleeve 6, the pin 132 is positioned in said slot 131a as illustrated in Fig. 13.

When the turntable T₁ is elevated to non-automatic or manual position under the control of handle extension 133a, the latter is moved into 15 engagement with the slot wall 133c of plate 133b. When thus elevated, said turntable T₁ is maintained by one of the holding pawls in a position high enough to cause the screw 180 to be as high as the aforesaid predetermined level whereby the 20 lever 43 is positioned for coaction with the depending flange 165e of lever 165. Said last named turntable position is slightly higher than is occupied by said turntable T₁ when sound is being reproduced from the lowermost record 25 thereon with the mechanism in condition for subsequent automatic operation and not for control of the lever 165.

When the screw 180 is removed from the cam surface 44e of lever 44, the levers 43 and 44 automatically return to the position illustrated in Fig. 3 under the influence of spring 178, the end of nose 43a of lever 43 riding along the sloping surface 44b of lever 44.

As illustrated particularly in Figs. 2 and 3, a 35 plurality of bell crank levers 183, 184 and 185 are spaced above the upper surface of frame member 1 and are pivoted on the respective members 186 upstanding from the latter.

The lever 183 is suitably biased in a clockwise 40 direction, Figs. 2 and 3, as by a helical spring 187, one end of which is connected to a lug upstanding from one leg thereof and the other arm of which is connected to a pin 188 upstanding from the frame member 1, said pin 188 limiting clockwise 45 movement, Figs. 2 and 3, of said lever 183.

The levers 184 and 185 are each suitably biased in counter-clockwise direction, Figs. 2 and 3, as by the helical springs 189 connected, respectively thereto and to the upstanding pins 190, all in the 50 same manner as described above in connection with the spring 187, said pins 190 limiting counterclockwise movement, Figs. 2 and 3, of said levers 184 and 185.

In the form of my invention herein disclosed, 55 the aforesaid levers 183, 184 and 185 are adapted for manual operation. To this end, any suitable arrangement may be utilized, and, as herein illustrated, slideable actuating members 191, 192 and 193 are provided for coaction, respectively, 60 with the levers 183, 184 and 185. Said members 191, 192, and 193 are slideable in suitable passages provided in the front wall of casing C and each is suitably biased toward the exterior of said casing C, as by helical springs 194 disposed around 65 reduced shanks of the respective members 191, 192 and 193 and exerting thrusts thereon tending to move them outwardly. Inwardly of the casing C, the members 191, 192 and 193 are shaped 70 for engagement with the closely adjacent legs of the respective levers 183, 184 and 185.

The member 191 and lever 183 are utilizable when it is desired to reproduce sound in succession from the topmost record on the turntable 75

provided that a plurality of records are disposed thereon.

In accordance with this phase of my invention, that leg of the lever 183 removed from the member 191 has one end of a link 195 pivoted thereto, the other end of said link 195 being pivoted to one arm 196a of a U-shaped lever 196 pivoted on a member 197 upstanding from the frame member 1. The other arm 196b of lever 196 comprises an upstanding lug or flange 196c and a curved surface 196d. Disposed on a boss 1f upstanding from the frame member 1 and pivoted thereto by a member 198 is a lever 199 having a ledge section 199a and a depending lug or flange 199b at one end thereof. Lever 199, at its end removed from flange 199b, comprises a depending section 199c in which a screw 200 is threaded. Lever 199 and screw 200 are suitably biased in a clockwise direction, Figs. 2 and 3, as by a helical spring 201, one end of which is connected to a lug upstanding therefrom and the other end of which is connected to a pin 202 upstanding from the boss to which lever 199 is pivoted, said pin 202 limiting clockwise movement, Figs. 2 and 3, of lever 199.

Referring particularly to Figs. 2, 3 and 11, a lug or flange 57a is shown as depending from the aforesaid arm 57 which, as described, is carried by and movable with the shaft 58. Lug 57a is coactable with the aforesaid screw 200, as herein-after described.

Any time during a period when sound is being reproduced, the member 191 may be operated against the force of its spring 194 should it be desired to again reproduce sound from said top-most record before removal thereof from the turntable.

When the member 191 is operated as just described, the lever 183 is swung counter-clockwise, Figs. 2 and 3, storing energy in the spring 187 and moving the link 195 from right to left, Figs. 2 and 3. As a result, lever 196 is swung clockwise, Figs. 2 and 3, and the lug 196c of its arm 196b is latched over the ledge section 199a of lever 199, the latter swinging counter-clockwise, Figs. 2 and 3, to a slight extent to permit the described movement of lever 196.

When lever 196 is moved to the position just described, the curved surface 196d of its arm 196b engages the reduced end of the tail section 73a of the ejector rod 73. As a result, the latter is swung to some extent in a clockwise direction, Fig. 11, and held in the position to which swung because of the latching engagement between the levers 196 and 199.

At the conclusion of said last named period of sound reproduction, a period of automatic operation is initiated as heretofore described. As usual, all of the cams move through their cycles of 360 degrees each and, as regards elevation of the sound box S, the movement is as heretofore described; as regards movement of said sound box S first from the turntable center and then toward the same until its stylus is just within the periphery of said topmost record, the movement is likewise the same as heretofore described.

However, in two important respects, the movement is different from that heretofore described. Since, the ejector arm 73 has been swung clockwise, Fig. 11, and so held, the member 75 has been elevated to sufficient extent that it does not engage the periphery of the topmost record but is moved thereabove by rod 73 in a counter-clockwise direction, Fig. 1, under the control of spring 55 and then counter-clockwise, Fig. 1, under the control of cam K. Accordingly, said topmost

record is not removed from the turntable at this time. Moreover, when the ejector rod 73 moves counter-clockwise as just described, the arm 67 of shaft 58 moves counter-clockwise, Fig. 12, to move the lever 69 clockwise, Fig. 12, and thereby disengage the pawl 120 from the ratchet member 116. When movement of rod 73 is not impeded by the topmost record, this action of lever 69 occurs early in the cycle of automatic operation and before the cam K4 has started to move the ratchet member 116 through the pawl 120. Accordingly, the turntable is not elevated at this time.

Otherwise than as stated, the action is the same as heretofore described, the sound box 15 stylus twice and in succession coacting with the same topmost record to twice reproduce sound therefrom.

The link 56 moves the arm 57 counter-clockwise, Figs. 2 and 3, when moving the rod 73 in the same direction, Fig. 1. As the arm 57 moves nearly to the end of its just described path, the lug 57a thereof engages the screw 200 to swing the lever 199 in a counter-clockwise direction, Figs. 2 and 3, against the action of spring 201 which returns the lever 199 into engagement with stop 202 when lug 57a recedes. As a result, the lever 196, link 195, and lever 183 are restored to the respective positions thereof shown in Figs. 2 and 3 under the influence of spring 187. Accordingly, the tail section 73a of rod 73 is released and the latter is permitted to swing, under the influence of gravity, to its normal position as determined by the screw 73.

With the parts thus restored to their normal positions, initiation of the next automatic cycle of operation will result in the discharge from the turntable of the record from which sound has twice been reproduced unless, in the meantime, the member 191 is actuated to perform the function heretofore specifically described.

As hereinbefore described, with but one record on the turntable, the eccentric groove thereof opens the switch contact members and does not initiate a cycle of automatic operation unless the configuration of said record is abnormal as hereinbefore described. Hence, reproduction of the lowermost record on the turntable may not be repeated unless said lowermost record is one of abnormal configuration causing initiation of a succeeding cycle of automatic operation.

The member 192 and lever 184 are operated should it be desirable to immediately terminate the sound being reproduced from the topmost record R and to initiate a period of sound reproduction from that record immediately beneath said topmost record.

In accordance with this phase of my invention, that arm of lever 184 removed from the member 192 has one end of a link 203 pivoted thereto, the other end of said link 203 being pivoted to one end of a lever 204 spaced above the upper surface of frame member 1 and pivoted on a member 205 upstanding therefrom. The end of lever 204 removed from the link 203 comprises a section 204a coactable with an angular flange 43b of the aforesaid lever 43.

If at any time during a period of sound reproduction, it becomes desirable to immediately terminate said sound reproduction, the member 192 may be operated against the force of its spring 194 to swing the lever 184 in a clockwise direction, Figs. 2 and 3, storing energy in its spring 189 and moving the link 203 from left to right, Figs. 2 and 3. As a result, the lever 204 is swung

in a counter-clockwise direction, Figs. 2 and 3, and at its section 204a engages the flange 43b of lever 43 to move the latter from right to left, Figs. 2 and 3, whereby engagement is effected with the 5 lug 45a of lever 45. As a result, lever 45 is swung counter-clockwise, Figs. 2 and 3, and a cycle of automatic operation is immediately initiated wherein the operations are as first described herein and whereby the topmost record is discharged from the turntable and the sound box stylus *s* brought into the beginning of the spiral sound reproducing groove of the next lowermost record.

When lever 43 is moved from right to left, 15 Figs. 2 and 3, as just described, the lever 37 was moved therewith and swung in a clockwise direction, Figs. 2 and 3; as a result, energy was stored in the spring 41. When pressure on the member 192 is released, lever 184, link 203 and lever 204 20 return to the respective positions thereof illustrated in Figs. 2 and 3 under the influence of spring 189. At the same time, levers 37 and 43 return to the positions shown in Figs. 2 and 3 wherein lever 37 engages the post 42.

Should the member 192 be operated while sound is being reproduced from the last record on the turntable, ordinarily, the switch contact members will be opened. This follows because, when lever 43 is swung clockwise, Figs. 2 and 3, 30 the turntable has been moved into its uppermost position, all as hereinbefore described, provided that the lowermost record thereon is not one of abnormal configuration. However, it may be desirable to so proportion the parts that clockwise movement as just described of lever 43 removes the flange 43b thereof out of the path of the section 204a of lever 204. Should this arrangement be adopted, operation of member 192 while sound is being reproduced from the lowermost record 40 on the turntable is without effect on any of the automatic mechanism.

When the member 193 is operated against the force of its spring 194, the lever 185 is swung clockwise, Figs. 2 and 3, storing energy in its spring 189 and, at an angular section 185a thereof, engaging the section 165g of lever 165. As a result, the lever 165 is swung counter-clockwise, Figs. 2 and 3, whereby the dog 164 is operated to open the switch contact members and discontinue operation of the motive device M. In response to such operation of the lever 165, the disk 172 and lever 176 swing, in response to disengagement of the nose of lever 176 from the adjacent end of lever arm 165h and under the influence of spring 177, in a counterclockwise direction, Figs. 2 and 3. Therefore, when next the motive device M is to be started, the lever 176 must be moved clockwise, Figs. 2 and 3, to the position illustrated therein.

As illustrated particularly in Fig. 2, the actuating extension 176b of lever 176 extends from beneath the turntable to a position adapted for convenient operation. The switch control mechanism comprising the member 193, therefore and ordinarily, is alternative with the switch lever 176. However, said member 193 is accessible even though the casing cover C1 is in its closed position whereas the lever 176 is not thus accessible.

The hereinbefore described lever 45, it will be noted particularly in Figs. 2 and 3, comprises an arm 45f terminating in a hook-shaped end 45g. Whenever the lever 45 is operated in any of the ways hereinbefore described to initiate a cycle of automatic operation, the hook-shaped end 45g of lever 45 moves into the path of flange 176a

of lever 176. Accordingly, during persistence of any automatic cycle of operation, neither the extension 176b nor the member 193 may be operated to open the switch contact members. In other words, operation of the motive device M 5 may be discontinued only while the mechanism is "out of cycle".

As hereinbefore described, operation of the arm 143, Figs. 13 and 14, occurs in response to depression of the rod 137 carried by the handle 10 section 133a. Also, as described, the arm 143 is pivoted on and movable with the shaft or member 144.

Referring particularly to Fig. 15, the shaft 144 is shown as having a lever 206 pinned or otherwise suitably secured thereto for movement therewith, the lever arms 206a and 206c projecting upwardly and being movable through an opening 207 in the frame member 1. One arm 206a of lever 206 comprises, at its upper end, a lateral 15 flange 206b having threaded therethrough a screw 208 which coacts with a depending section 43c of the aforesaid lever 43. The other arm 206c of lever 206 comprises an angular section 206d coactable with the aforesaid flange 199b of lever 25 199.

As hereinbefore described, depression of rod 137 causes movement of arm 143 in a clockwise direction, Fig. 3, to disengage all of the pawls from the ratchet member 116. In response to 30 such movement of arm 143, the shaft 144 is also moved in a clockwise direction, Figs. 13 and 15, the lever 206 moving in the same direction Fig. 15. As a result, the screw 208 engages the depending section 43c of lever 43 and angular 35 lever section 206d engages the flange 199b of lever 199. Accordingly, the lever 43, if not in the position shown in Figs. 2 and 3, will be moved to such position. At the same time, the lever 199 is swung counter-clockwise, Figs. 2 and 40 3, to unlatch the lever 196 should the latter have been latched in engagement therewith.

In this manner each time that the rod 137 is depressed, to release all of the pawls, a control is applied to the lever 199 and likewise to 45 the lever 43, if the latter is not in position for automatic operation.

In general, the operation is as follows:

With a plurality of records R on the turntable and with the stylus *s* of sound box S engaging 50 the spiral sound reproducing groove of the topmost record R, sound is reproduced until just before the time that said stylus *s* engages the eccentric groove *e* of said record R. During this or any period of sound reproduction, the automatic mechanism is "out of cycle".

Under the influence of the eccentric groove *e* of said topmost record R, the sound box S and tone arm 25 are moved in a direction the reverse 55 of that taken thereby during the period of sound reproduction. As a result, lever 45 is swung in a counter-clockwise direction, Figs. 2 and 3, to permit engagement of the clutch crescent tooth 10 with the clutch wheel 7. Thus, the cam shafts 20 and 50 are connected to the main drive shaft 5 60 and at this time the automatic mechanism is "in cycle", each of said cam shafts moving through an angle of 360 degrees during each cycle of automatic operation.

As illustrated particularly by the timing chart 70 of Fig. 20, the cam K3 immediately becomes effective to elevate the sound box S from the topmost record R on the turntable, the sound box stylus *s*, however, not separating from said record R until after engagement has been effected 75

between the stop members 31 and 32. After the cam K3 has moved through an angle of approximately 47 degrees, the sound box S reaches its fully elevated position. Until near the close of 5 the cycle, said sound box S remains elevated, the cam K3 releasing control thereof only after it has moved through an angle of approximately 353 degrees. Just prior to attainment of this movement, the sound box stylus s has engaged the 10 record from which sound is next to be reproduced after which the stop members 31 and 32 are brought to their separated position.

Soon after the cycle of automatic operation is 15 initiated, the low surface of cam K permits progressive movement of lever 53 in a clockwise direction, Figs. 2 and 3, under the influence of spring 55. As a result, the ejector rod 73 is moved in a counter-clockwise direction, Fig. 1. If the topmost record R on the turntable is one 20 having a diameter of twelve inches, the periphery thereof is engaged by the rim 75a of member 75 after the cam K has moved through an angle of approximately 35 degrees. However, if the topmost record R is one having a diameter of ten 25 inches, the periphery thereof is engaged by said member 75 after the cam K has moved through an angle of approximately 42 degrees. As a result, in either case, the member 75, rod 73 and the parts in the mechanical train leading to and including the lever 53 remain stationary for an 30 interval.

After the cam K4 has moved through an angle 35 of approximately 44 degrees, the turntable starts to rise to free the topmost record R therefrom, all as hereinbefore described.

In response to the release thus effected of said topmost record R, the member 75 and rod 73 suddenly resume movement in a counter-clockwise direction, Fig. 1, and said topmost record R 40 is passed to the side of casing C, a roller 213 preferably being utilized to facilitate this action, said roller being mounted on a rod or member 214 extending through the motor board m and secured to the frame member 1.

45 When the topmost record R is released from the turntable, the resulting counter-clockwise movement of rod 73 causes said turntable to be disconnected from the elevating pawl 120, all as hereinbefore described. Cam K4, thereafter is 50 functionless during that particular cycle although as illustrated, in Fig. 20, the highest area thereof coacts with its roller 118 after movement through an angle of approximately 100 degrees and when said cam K4 has moved thru an angle 55 of approximately 163 degrees, the last mentioned roller 118 has been lowered to its normal position carrying with it the pawl 120 which idles over the teeth of ratchet member 116 as it descends.

As shown in Fig. 20, the cam K when it has 60 moved through an angle of approximately 100 degrees, coacts with the roller 54 of lever 53 to move the latter in a counter-clockwise direction, Figs. 1 and 2, storing energy in the spring 55. This action continues until the cam K has moved 65 through an angle of approximately 190 degrees. In response to such counter-clockwise movement of lever 53 and through the hereinbefore described chain of mechanism, the rod 73 and member 75 are moved in a clockwise direction, 70 Fig. 1. Furthermore, during such movement, the section 33c of member 33 is gripped between the levers 146 and 147 as shown in Fig. 18 and the sound box S and its stylus s are carried laterally from the turntable center to a position wherein 75 it is directly above a point disposed without the

periphery of the topmost record R on the turntable no matter whether that is one having a diameter of ten or twelve inches.

During continued movement of cam K beyond its 190 degree position, a low area thereof causes 5 clockwise movement, Figs. 2 and 3, of lever 53 under the influence of spring 55. As a result, the rod 73 and member 75 are again moved in a counter-clockwise direction, Fig. 1, until the rim 75a of member 75 engages the periphery of 10 the now topmost record R on the turntable, this being the next record from which sound is to be reproduced. By this action, such counter-clockwise movement of member 75 is discontinued, movement of cam K continuing, said last 15 mentioned low area thereof slightly receding from the roller 54. The sound box S, through the intervening mechanism comprising the levers 146 and 147, remains connected to the rod 73 as it thus moves and when the latter is brought to 20 rest by the record R from which sound is next to be reproduced as just described, the sound box stylus s is positioned vertically above a point between the peripheral edge of said record and the spiral sound reproducing groove structure. 25

This action is effected no matter whether said record from which sound is next to be reproduced is one having a diameter of twelve or ten inches since if said last named record is one having a diameter of twelve inches, the member 75 is 30 brought to rest thereby slightly earlier than if the diameter thereof is ten inches.

After the cam K3 has moved through an angle of approximately 220 degrees, it functions to lower the sound box S sufficiently to disengage 35 the section 33c of member 33 from between the levers 146 and 147 but insufficiently, at this time, to cause engagement between the sound box stylus s and the topmost record R from which sound is next to be reproduced. The 40 aforesaid section 33c is thus disengaged from the levers 146 and 147 prior to the time that cam K has moved through an angle of approximately 243 degrees for, at this time, said cam K functions to swing the ejector arm 73 in a clockwise 45 direction, Fig. 1. As a result of the foregoing action, the sound box S is left in proper position above the record from which sound is next to be reproduced.

When the arm 73 is swung clockwise as just 50 described, the levers 146 and 147 and the parts directly associated therewith are moved from left to right, Fig. 19, until by engagement effected between the screw 156 and lateral section 146d of lever 146, the various parts comprising the levers 146 and 147 are latched into the relation shown in Fig. 16, this relation being occupied thereby during those periods when the automatic mechanism is "out of cycle". Soon after the aforesaid latching relation is effected, 60 the cam K reaches the position illustrated in Fig. 2 where operation thereof is discontinued.

After cam K3 has moved through an angle of approximately 320 degrees, it lowers the sound box S toward the topmost record R and permits the sound box stylus s to engage said record between the peripheral edge thereof and the spiral sound reproducing groove structure. After engagement is thus effected the cam K3 lowers the tone arm 29 still further, to a slight 70 degree, and the stop members 31 and 32 are separated. Movement of cam K3 then continues until reaching the position in Fig. 5 which is in its "out of cycle" position.

As described, the hereinbefore described mem- 75

ber 33 which moves with the tone arm 29 comprises an arm 33a to which a resilient member 34 is secured, Fig. 3. When the sound box stylus s is positioned vertically above a point between the peripheral edge of the topmost record R and the spiral sound reproducing groove structure, the member 34 will be occupying a position counter-clockwise of that shown in Fig. 3. If said topmost record R is one having a diameter of twelve inches the extent of counter-clockwise movement will be slightly greater than if said record is one having a diameter of ten inches. When cam K3 lowers the sound box S the member 34 is also lowered and, if said topmost record 15 is one having a diameter of twelve inches, said member 34 will be positioned in the path of prong 89 of lever 84, Fig. 3, whereas if said topmost record R is one having a diameter of ten inches, said member 34 will be positioned in the path 20 of prong 88 of said lever 84.

Accordingly, just after the sound box stylus s is lowered into engagement with the topmost record R as described above, the high area 82 of cam K1 rocks the lever 83 in a counter-clockwise direction, Figs. 2 and 3, and either the prong 88 or 89 of said lever 83 engages the member 34, the particular prong depending on the diameter of said topmost record. When the member 34 is thus engaged, the arm 33a is swung in clockwise direction, Figs. 2 and 3, to similarly swing the tone arm 29, sound box S, and stylus s, the latter being fed gently into the spiral sound reproducing groove of said topmost record.

The aforesaid high area 82 of cam K1 immediately passes beyond the roller 83 of lever 84, said roller 83 entering the low area 81 of said cam K1 to effect swinging movement of lever 84 in a clockwise direction, Fig. 3. Simultaneously, lever 45 is also moved clockwise, Figs. 2 and 3 in response to movement of cam roller 80 into the low area 79 of cam K1. As a result of the action last named, the hook shaped end 45d of lever 45 is moved into the path of the clutch segment 10 to swing the latter on its pivot and disengage the tooth 10a thereof from the clutch wheel 7. Just as this is done, roller 86 of lever 84 comes into the path of and is engaged by the sloping surface 87 of disk 8. The cycle of automatic operation is now concluded and a period of sound reproduction ensues. At the conclusion thereof, the sound box stylus s passes from the spiral sound reproducing groove of said record into the eccentric e thereof whereby the succeeding cycle of automatic operation is initiated to cause, in automatic sequence, repetition of the steps herein described. However, if desired the automatic operation may be initiated at any time during the period of sound reproduction in response to operation of the member 192.

Although the machine or mechanism constructed in accordance with my invention is intended particularly for records wherein the spiral sound reproducing groove terminates in a circular groove eccentrically disposed with respect to the record center, it shall be understood that my invention is not to be thus limited. Under some circumstances, it may be desirable to successively initiate cycles of the automatic mechanism otherwise than by a control performed by the eccentric grooves on the respective records. Thus, for example, such control may be effected by the "Crowell" type of groove which comprises generally a large pitch spiral extending from the spiral sound reproducing groove and terminating in a circular

groove concentrically disposed with respect to the record center.

It shall also be understood that in no manner at all is my invention to be limited to the utilization of an acoustical or mechanical type of sound box 5 wherein sound waves originated by the sound box diaphragm are transmitted through a tone arm or taper tube and thence to an amplifying horn. In lieu of a sound box, as aforesaid, a sound reproducing instrumentality of any other desired 10 type may be utilized such, for example, as a "pick-up" of suitable or desired character. When a pick-up is thus utilized as well understood in the art, the stylus-actuated armature, or equivalent, thereof generates or modifies an electrical current 15 which controls the operation of any suitable loud speaker, or equivalent, disposed either in the same casing containing the automatic mechanism or more or less remote therefrom as desired.

Although but a single motive device has been 20 herein illustrated and described for rotating the turntable and operating the automatic mechanism, it shall be understood, if desired, that a plurality of motive devices may be utilized, one to rotate the turntable and another to operate 25 the automatic mechanism. For purposes of explanation, there has been incorporated into the drawings of this application, the timing chart or diagram illustrated in Fig. 20 together with references thereto in the specification proper. It 30 shall be understood that the timing arrangement thus illustrated and described is typical of but one of a number of different timing arrangements for accomplishing the purpose of my invention.

It shall also be understood that any or all of 35 the various hereinbefore described auxiliary features, as those controlled by the members 191, 192 and 193 together with the sets of mechanism comprised respectively therein may be omitted or utilized as desired.

Although the various controls have been hereinbefore described as performed mechanically, i. e., by levers, links, etc., it shall be understood that, as well, some or all of said controls may be performed electro-magnetically.

While my invention has been illustrated and described in connection with records R of different diameters, it shall be understood that as regards certain aspects thereof, it is not so limited. Hence, except as limited in the appended claims, 50 it shall be understood that my invention is broad and general as regards the diameter of records to be utilized and that, in connection with certain features, said records may be all of one diameter, if desired.

It shall be distinctly understood that the specific description and illustration of the application is to be taken merely as illustrative of one of the many forms of my invention. Thus, for example the turntable elevating mechanism together with the arrangement for removing records therefrom may depart widely from that herein disclosed. If desired a plurality of cams may be substituted for the herein disclosed cam K, one of said cams controlling lateral movement of the 65 sound box, or equivalent, and another of said cams controlling or effecting removal of the records from the turntable.

Still further, it shall be understood that operation of the motive device M may be discontinued otherwise than as herein described and that arrangements differing widely from that disclosed may be utilized for having the mechanism come to its non-automatic or manual state after the last period of sound reproduction.

Still further, it shall be understood that a turntable T1 and an associated disk R1, or structure looking to the attainment of the same function as by them performed may be incorporated in 5 automatic sound reproducing systems of many kinds and is not limited to those wherein a plurality of records are stacked upon a turntable.

It will be obvious that the members, such as the herein disclosed screws 65, 154, 156, 200, 208, 10 etc. are provided so that accurate adjustments 15 may be obtained.

While the invention has been described with respect to certain particular examples which give satisfactory results, it will be understood by those 15 skilled in the art after understanding the invention, that various changes and modifications may be made without departing from the spirit and scope of the invention and it is intended, therefore, in the appended claims to cover all such 20 changes and modifications.

What I claim is:

1. In a sound reproducing system, the combination with a turntable on which are grouped a plurality of phonograph records of different diameters, of means for automatically reproducing sound in succession from said records including a sound translating device, and means for automatically removing the topmost record of said group after a period of sound reproduction, said 25 last named means being subsequently automatically responsive to the diameter of the next successive topmost record of said group for controlling the positioning of said device at the beginning of said topmost record.

35 2. In a system for manipulating phonograph records of different diameters, the combination with a turntable including a turntable stem having a group of said records threaded thereon, means for successively elevating said turntable, to release the successive topmost records from 40 said stem, means effective after each record has been released from said stem for positively removing said record from the turntable, a sound translating device adapted to co-operate with 45 said successive topmost records, means independent of said turntable stem and said first named means effective after the respective steps of elevation of said turntable for controlling movement of said device to a position above playing position, and means for thereafter lowering 50 said device into playing position.

3. In a sound reproducing system, the combination with a turntable on which are grouped a plurality of phonograph records of different 55 diameters of means for automatically reproducing sound in succession from said records including a sound translating device, periodic reciprocal means automatically responsive to the diameter of the topmost record of said group 60 adapted for subsequently positioning said device above the beginning of said topmost record, means associated with said device whereby said reciprocal means is temporarily connected to said device during movement of said reciprocal 65 means in one direction, and means for thereafter lowering said device onto said record whereby said device is disconnected from said reciprocal member.

4. In a system for manipulating talking machine or phonograph records of different diameters, the combination with a turntable including an expandable stem carrying one of said records with said stem projecting through the center perforation thereof, of means for effecting relative movement between said turntable and said

stem to grip said record and to release the same from said stem, and means for removing said record from said turntable, said last named means comprising a member resiliently urged prior to disengagement thereof from said stem. 5

5. In a system for manipulating talking machine or phonograph records of different diameters, the combination with a turntable including an expandable stem carrying one of said records with said stem projecting through the center perforation thereof, of means for effecting relative movement between said turntable and said stem to grip said record and to release the same from said stem, and means for removing 15 said record from said turntable, said last named means comprising a spring, and a member biased by said spring into engagement with the periphery of said record.

6. In a system for manipulating talking machine or phonograph records, the combination with a turntable carrying one of said records and having its stem projecting through the center perforation thereof, of means for effecting relative movement between said turntable and said 25 stem to release said record from said stem, and means for removing said record from said turntable, said last named means comprising a cam, a spring, and a member biased by said spring into engagement with the periphery of said record, 30 said cam controlling said member.

7. In a system for manipulating talking machine or phonograph records, the combination with a turntable carrying one of said records and having its stem projecting through the center 35 perforation thereof, a spring, a member biased by said spring into engagement with the periphery of said record, a cam and a lever connected to said member and having a follower biased toward said cam by said spring, said record 40 acting with said member to temporarily hold it stationary and to maintain said follower spaced from said cam.

8. In a system for manipulating talking machine or phonograph records, the combination 45 with a turntable carrying one of said records and having its stem projecting through the center perforation thereof, a spring, a lever movable in substantially a horizontal plane and biased by said spring into engagement with the periphery 50 of said record, a cam, and a second lever connected to said first named lever and having a follower biased toward said cam by said spring, said record coacting with said first lever to temporarily hold it stationary and to maintain said 55 follower spaced from said cam.

9. In combination, a turntable having a plurality of talking machine or phonograph records of different diameters grouped thereon and an expandable stem projecting upwardly beyond the 60 upper surface of said turntable and extending through the center perforations of said records, means for expanding said stem to normally grip the uppermost one of said records, and means for effecting relative movement between said 65 turntable and the stem in successive steps the extent of which is determined by the thickness of successive records.

10. In combination, a turntable having a plurality of talking machine or phonograph records 70 of different diameters grouped thereon and an expandable stem projecting upwardly beyond the upper surface of said turntable and extending through the center perforations of said records, means for expanding said stem to normally grip 75

the uppermost records of said group, said stem being rotatable with said turntable, and means for effecting relative movement between said turntable and stem in successive steps the extent of which is determined by the thickness of successive records.

11. In combination, a turntable having a plurality of talking machine records of different diameters grouped thereon, an expansible stem projecting upwardly beyond the upper surface of said turntable and extending through the center perforations of said records, extensible means operable within said stem and adapted to normally expand said stem to engage with the adjacent surfaces of said records, and means for periodically elevating said turntable independently of said stem to free the uppermost record from said stem.

12. In combination, a turntable having a plurality of talking machine or phonograph records grouped thereon, a stem projecting upwardly beyond the upper surface of said turntable and extending through the center perforations of said records, said turntable being elevatable independently of said stem, said stem comprising spring fingers biased into engagement with adjacent surfaces of said record and means for nullifying such biasing action.

13. In combination, a turntable carrying a talking machine or phonograph record, a sound reproducing instrumentality movable across the face of said record to reproduce sound, and a pivoted rod operable after reproduction of a record has been completed for removing said record from said turntable and for controlling said sound reproducing instrumentality for movement to a position adjacent the periphery of said turntable and then in a reverse direction to playing position.

14. In combination, a turntable carrying a talking machine or phonograph record, a sound reproducing instrumentality movable across the face of said record to reproduce sound, and a pivoted rod having a record engaging member rotatably mounted on the free end thereof and adapted to swing in one direction for removing said record from said turntable after said record has been reproduced, said rod thereafter controlling said sound reproducing instrumentality for movement to a position adjacent the periphery of said turntable and then in a reverse direction to playing position.

15. In combination, a turntable carrying a talking machine or phonograph record, a sound reproducing instrumentality movable across the face of said record to reproduce sound, and a pivoted rod movable after reproduction of a record has been completed in one direction for removing said record from said turntable and in a direction the reverse of said one direction for controlling said sound reproducing instrumentality for movement to a position adjacent the periphery of said turntable and then in a reverse direction to playing position.

16. In combination, a turntable carrying a talking machine or phonograph record, a sound reproducing instrumentality movable across the face of said record to reproduce sound, an oscillatory ejector rod, means effective after the period of sound reproduction for moving said rod in one direction to remove said record from said turntable, and means for thereafter moving said rod in a direction the reverse of said one direction, said sound reproducing instrumentality moving with said rod during last named move-

ment thereof first to a position adjacent the periphery of said turntable and then in a reverse direction to playing position.

17. In combination, a turntable carrying a talking machine or phonograph record, a sound reproducing instrumentality movable in one direction across the face of said record to reproduce sound, and means effective after the period of sound reproduction for moving said sound reproducing instrumentality in a direction the reverse of said one direction, said means thereafter moving said sound reproducing instrumentality in said one direction toward the periphery of another record on said turntable, said means comprising a pivoted rod for sliding a record from said turntable after a period of sound reproduction.

18. In combination, a turntable carrying a talking machine or phonograph record, a sound reproducing instrumentality movable in one direction across the face of said record to reproduce sound, and means effective after the period of sound reproduction for moving said sound reproducing instrumentality in a direction the reverse of said one direction, said means thereafter moving said sound reproducing instrumentality in said one direction toward the periphery of another record on said turntable, said means comprising an oscillatory member for removing a record from said turntable by sliding movement only after a period of sound reproduction.

19. Talking machine or phonograph mechanism comprising an oscillatory member, a sound reproducing instrumentality carried by said member, a turntable carrying a talking machine or phonograph record, a pivoted rod for sliding said record from said turntable, and means for periodically connecting said oscillatory member to said rod whereby said oscillatory member is positioned by said rod first adjacent the periphery of said turntable and subsequently in playing position for another record, said member and said rod when disconnected being movable independently of each other.

20. In an automatic phonograph, a turntable adapted to support a stack of records, a reproducer, unitary means for removing the uppermost record from said stack of records after a period of sound reproduction, and means whereby said record removing means cooperates with the periphery of the next succeeding record to determine the positioning of the reproducer to reproduce sound from the said succeeding record.

21. In a sound reproducing system, the combination with a turntable having grouped thereon talking machine or phonograph records of different diameters, and a sound reproducing instrumentality coactable with the topmost record of the group of records to reproduce sound, of a member for moving said topmost record from said turntable after the period of sound reproduction, said member coacting with the periphery of the next lower record on said turntable to determine the position to be taken by said sound reproducing instrumentality just prior to another period of sound reproduction, said sound reproducing instrumentality being connected to said member for movement therewith during the interval between said periods of sound reproduction.

22. In a sound reproducing system, the combination with a turntable having a plurality of talking machine or phonograph records grouped

thereon, of means for reproducing sound from the topmost record of the group of records, and means comprising a pawl and ratchet mechanism for elevating said turntable after the period of sound reproduction an amount determined by the thickness of said topmost record.

23. In a sound reproducing system, the combination with a turntable having a plurality of talking machine or phonograph records grouped thereon, of means for reproducing sound from the topmost record of the group of records, and means comprising a pawl and ratchet mechanism for elevating said turntable after the period of sound reproduction, and means for rendering said mechanism inoperative after said turntable has been elevated an amount corresponding with the thickness of said topmost record.

24. In a sound reproducing system, the combination with an elevatable turntable having a plurality of talking machine or phonograph records grouped thereon, said turntable having non-elevatable stem structure projecting through the record perforations, of means for reproducing sound from the topmost record of the group of records, means for elevating said turntable after the period of sound reproduction comprising a pawl and ratchet mechanism, and means for disengaging said pawl from said ratchet whereby, elevation of said turntable is discontinued in response to movement of said topmost record beyond said stem structure.

25. In combination, a talking machine or phonograph turntable, pawl and ratchet mechanism for elevating said turntable, and means for disengaging said pawl from said ratchet after predetermined elevation of said turntable.

26. In combination, a talking machine or phonograph turntable, pawl and ratchet mechanism for elevating said turntable, means for disengaging said pawl from said ratchet, and pawl structure for holding said turntable in an elevated position during disengagement of said first named pawl from said ratchet.

27. The combination with a turntable having a plurality of talking machine or phonograph records grouped thereon, means for reproducing sound from the topmost record of the group of records, and a member for removing said topmost record from said turntable after the period of sound reproduction, of clutch mechanism for elevating said turntable after the period of sound reproduction, said member, while removing said topmost record, causing disengagement of said clutch mechanism from said turntable.

28. The combination with a turntable having a plurality of talking machine or phonograph records grouped thereon, means for reproducing sound from the topmost record of the group of records, and a member for removing said topmost record from said turntable after the period of sound reproduction, of clutch mechanism comprising a pawl and ratchet for elevating said turntable after the period of sound reproduction, and means for retaining said turntable in its elevated position, said member, while removing said topmost record, causing disengagement of said pawl from said ratchet.

29. In combination, a turntable having a plurality of talking machine or phonograph records grouped thereon, means for automatically elevating said turntable after reproduction of sound from the respective topmost records thereon, means for retaining said turntable in its elevated position, and manually controlled means for elevating or lowering said turntable, said last

named means comprising a device for placing said automatic elevating means and said retaining means in non-operative conditions.

30. In combination, a turntable having a plurality of talking machine or phonograph records grouped thereon, means for elevating said turntable after reproduction of sound from the respective topmost records thereon, and manually controlled means for elevating or lowering said turntable, said last named means comprising a hand lever moved step-by-step by said first named means.

31. In combination, a turntable having a plurality of talking machine or phonograph records grouped thereon, a motor board, means below said motor board for automatically elevating said turntable after reproduction of sound from the respective topmost records, manually controlled means for elevating or lowering said turntable independently of said automatic means, said last named means comprising a hand lever terminating above said motor board and oscillatable in substantially a vertical plane, and stops for limiting movement of said lever.

32. In combination, an elevatable turntable having a group of talking machine or phonograph records disposed thereon, means for elevating said turntable, means for retaining said turntable in an elevated position, and manually controlled means for moving said turntable while temporarily placing both of said first named means in non-operative conditions.

33. A device for removing a talking machine or phonograph record from a turntable, said device comprising a rotatable member adapted to rotate in contact with the periphery of said record, and a second rotatable member projecting therefrom and coactable with the top face of said record.

34. In a sound reproducing system, a turntable having a plurality of talking machine or phonograph records grouped thereon, an instrumentality for reproducing sound upon movement in one direction across the face of the topmost record of the group of records, means effective at the termination of the period of sound reproduction for elevating said instrumentality, a member for removing said topmost record from said turntable, said instrumentality while held elevated being connected to said member for lateral movement from the turntable center and then in reverse direction until positioned vertically above a point just within the periphery of the now topmost record on said turntable, said instrumentality while in said last named position being disconnected from said member and lowered into engagement with said last named topmost record, and means for moving said instrumentality into the spiral sound reproducing groove on said last named record.

35. In a sound reproducing system, the combination with a turntable having a talking machine or phonograph record disposed thereon, an instrumentality for reproducing sound upon movement in one direction across the face of said record, means effective at the termination of the period of sound reproduction for elevating said instrumentality, means for moving said instrumentality, while held elevated, laterally from the turntable center and then in reverse direction until positioned vertically above a point just within the periphery of a record on said turntable, said instrumentality being then lowered from the control of and disconnected from said second named means, said instrumentality there-

after being lowered into engagement with said last named record, and means for moving said instrumentality into the spiral sound reproducing groove on said last named record.

- 5 36. In a sound reproducing system, a turntable having a plurality of talking machine or phonograph records grouped thereon, automatic mechanism for successively removing the topmost records of the group of records from said turntable after reproduction of sound therefrom, a motive device for operating said turntable and said automatic mechanism, and means for automatically discontinuing the operation of said motive device after sound has been reproduced from the last record on said turntable and before said last record has been removed from the turntable, said means being controlled by the effective thickness of said last record to discontinue operation of said motive device.
- 20 37. In a sound reproducing system, a turntable having a plurality of talking machine or phonograph records grouped thereon, automatic mechanism for successively removing the topmost records of the group of records from said turntable after reproduction of sound therefrom, a motive device for operating said turntable and said automatic mechanism, and means for automatically discontinuing the operation of said motive device after sound has been reproduced from the last record on said turntable, said means being controlled by the effective thickness of said last record to discontinue operation of said motive device either before or after removal thereof from said turntable.
- 35 38. In a sound reproducing system, a turntable having a plurality of talking machine or phonograph records grouped thereon, automatic mechanism for successively removing the respective topmost records of the group of records from said turntable after reproduction of sound therefrom, said automatic mechanism including an expandable turntable stem adapted for gripping said records at the center perforations, a motive device for operating said turntable and said automatic mechanism, and means for discontinuing operation of said motive device, said turntable stem being rendered ineffective to grip said records when operation of said motive device is discontinued.
- 50 39. In a sound reproducing system, a turntable having a plurality of talking machine or phonograph records grouped thereon, automatic mechanism for successively reproducing sound from the respective topmost records of the group of records, said automatic mechanism comprising a pivoted member movable laterally after each period of sound reproduction and coacting directly with the then topmost record on said turntable to effect removal thereof from said turntable, and means for swinging said member on its pivot to a position where it clears the then

topmost record on said turntable whereby sound may be reproduced in succession from the same record on said turntable.

40. A phonograph turntable having on its upper surface a spiral groove of substantially greater pitch than an ordinary sound reproducing spiral record groove, a motor for driving said turntable including control means for said motor, said turntable groove being arranged to co-operate with the stylus of a sound reproducing instrumental whereby to control the travel of said instrumentality over said turntable, said turntable groove terminating in a circular control groove effective to impart to said instrumentality a motor controlling movement, and means responsive to said motor controlling movement adapted to actuate said motor control means.

41. A phonograph turntable having on its upper surface a spiral groove of substantially greater pitch than an ordinary sound reproducing spiral record groove, a motor for driving said turntable including control means for said motor, said turntable groove being arranged to co-operate with the stylus of a sound reproducing instrumental whereby to control the travel of said instrumentality over said turntable, said turntable groove terminating, adjacent the turntable center, in a circular control groove effective to impart to said instrumentality a motor controlling movement, and means responsive to said motor controlling movement adapted to actuate said motor control means.

42. In a talking machine of the type adapted to automatically reproduce a plurality of records in succession and in which the automatic operations are initiated by coaction of the reproducing stylus with the record groove control, a turntable having a disk permanently secured thereto, said disk being formed of record material and having a rapid lead-in groove thereon, and said lead-in groove terminating in an eccentrically disposed control groove adapted to coact with the reproducing stylus to actuate said stylus to initiate a cycle of automatic operations.

43. A phonograph turntable having on its upper surface a spiral groove of substantially greater pitch than an ordinary sound reproducing spiral record groove, a motor for driving said turntable including means for controlling said motor, said turntable groove being arranged to co-operate with the stylus of a sound reproducing instrumental whereby to control the travel of said instrumentality over said turntable, said turntable groove terminating, adjacent the turntable center, in a circular control groove eccentrically arranged with respect to said turntable center and effective to impart to said instrumentality a reverse movement, and means responsive to said reverse movement adapted to actuate said motor controlling means.

RUDOLPH F. MALLINA.
